PRINTING MACHINE

Walter T. Gollwitzer, Euclid, Ohio, assignor to
Addressograph-Multigraph Corporation, Cleve-
land, Ohio, a corporation of Delaware

Application October 25, 1941, Serial No. 416,548

22 Claims. (Cl. 101—58)

1

This application is a continuation in part of my copending application Serial No. 221,841, filed July 28, 1938.

This invention relates generally to printing and like machines through which printing, printing and control or like devices are sequentially fed to have printing operations performed therefrom, and more particularly this invention relates to the platen mechanism of such machines whereby the desired printing impressions are made from the printing means of such devices.

In the use of printing machines of this character the printing impressions which are to be made usually pertain to identification data such as names, addresses and like information, and the printing impressions are made upon webs, sheets, business instruments and the like directly from the printing means of such printing, printing and control or like devices which are passed through the machine. The printing devices from which the printing impressions are made may take many different forms, but in most instances each printing device embodies a plurality of lines of printing characters, such as embossed type, from which printing impressions may be made upon a sheet, business form or the like. While a wide variety of printing devices may be employed in machines of the general character to which this invention pertains, the printing device disclosed in Mohler Patent No. 1,812,894, patented July 7, 1931, is typical of one form of printing device which may be employed. Another generally similar form of printing device adapted for use in connection with the platen mechanism of the present invention is disclosed in my Patent No. 2,132,412, patented October 11, 1938. A printing device of this character includes a rectangular carrier or frame having an embossable metal printing plate removably retained in position thereon, type characters being embossed on such a plate to appear in relief on the operative face thereof. Printing devices of a one-piece character may also be employed, such a printing device being shown in Duncan Patent No. 1,026,246, patented May 14, 1912, and in such one-piece printing devices the embossed type characters are formed directly in the single sheet of metal which forms the printing device. In so far as some aspects of the present invention are concerned, the printing devices may be of the kind wherein type or printing characters are formed on suitable stencil paper, carried by frame of cardboard or other material, and in such an instance the type characters are inked prior to the

2

time when they are brought into printing cooperation with a sheet or business form.

In a printing device of the various types hereinabove referred to, the body of the printing device may embody control means representing variable control data related to the identification data represented by the printing characters carried on each such device, and this control data may be utilized for various control purposes in producing the complete business instrument pertaining to each such device.

When the printing devices of the aforesaid character are passed through a printing machine or the like, the printing impressions are made directly from the type characters carried by the printing devices. These printing impressions usually pertain to identifications such as names, addresses and the like, and it will be evident that the number of type characters necessary to provide each such identification may vary substantially so that the printing impression made from one printing device may involve but a few type characters while the printing impressions made from another printing device may involve a large number of type characters. Such printing impressions are usually made through the use of a platen means which presses a sheet into printing cooperation with the type characters embodied in the printing devices and in prior practice it has been found that the operation of such platen means has caused a heavier printing impression to be made when but a few type characters are present on a printing device than was made when a large number of type characters are present on the printing device.

An important object of this invention is, therefore, to make uniform printing impressions from the printing means of such printing devices even though there may be a substantial variation in the number of type characters embodied in the printing devices which are successively passed through the printing machine.

A further object of the invention is to enable the platen means of such a printing machine to be actuated by hydraulic means, and more particularly it is an object of the invention to actuate the platen means by a closed hydraulic system so that uniformity of the printing impressions is assured. Further objects related to the foregoing are to insure against the presence of air or other elastic fluid in such hydraulic platen actuating means; to provide a constant make-up supply of hydraulic liquid; to periodically introduce an excess of such make-up liquid into the system; and to enable such excess liquid to be

returned to the make-up supply in a cycle of platen operation.

A further object of the invention is to limit the movement of the platen or other impression making member of such a printing machine toward the type characters so as to stop the platen in a definite and ascertained position in each operation thereof to thereby insure that uniform impressions will be produced. A further object is to arrange the support for the printing devices and the support for the platen in a common structure so that the pressure incident to the operation of the platen will be so distributed throughout the structure that the strains incident to the printing operation cannot produce uneven printing impressions. Further objects related to the foregoing are to relieve the hydraulic pressure in the absence of a sheet below the platen to thereby prevent the formation of offsets on platen or other impression making member, and to provide a novel and efficient platen structure for use in printing and like machines.

Other objects and advantages of this invention will become apparent from the following claims, taken in connection with the following description and the accompanying drawings which disclose certain preferred embodiments of the invention.

In the drawings:

Fig. 1 is a front elevational view of a machine adapted for producing business instruments and embodying platen mechanism which includes the features of the invention;

Fig. 2 is a plan view of the machine shown in Fig. 1;

Fig. 3 is a front face view of a printing and control device adapted for use with the machine shown in Fig. 1;

Figs. 3A and 3B are fragmentary elevational views of control cards that may be used with the printing and control devices shown in Fig. 3;

Fig. 4 is a chart of the code under which perforations are made in the control areas of the printing and control devices such as that shown in Fig. 3;

Fig. 5 is an elevational view of a typical business instrument produced by the machine shown in Figs. 1 and 2 of the drawings;

Fig. 6 is a fragmentary elevational view of a proof sheet such as may be produced in the machine shown in Figs. 1 and 2;

Fig. 7 is a fragmental vertical sectional view taken substantially along the line 7-7 of Fig. 2 and illustrating the platen and its hydraulic actuating system;

Fig. 8 is an enlarged sectional view taken along the line 8-8 of Fig. 7;

Fig. 9 is a vertical sectional view of the metering pump, the view being taken substantially along the line 9-9 of Fig. 7;

Fig. 10 is a plan section showing the top of the metering pump and taken substantially along the line 10-10 of Fig. 7;

Fig. 11 is a sectional view taken along the line 11-11 of Fig. 9;

Fig. 12 is a vertical sectional view taken along the line 12-12 of Fig. 7;

Fig. 13 is a sectional view taken along the line 13-13 of Fig. 12;

Figs. 14 and 15 are diagrammatic views illustrating the platen mechanism in two different positions;

Fig. 16 is a schematic wiring diagram illustrating the electrical connections whereby the platen mechanism is controlled;

Figs. 17 to 17A are vertical sectional views adapted to be read together as a single view and showing an alternative form of platen mechanism and hydraulic actuating means therefor;

Fig. 18 is a fragmental plan view of one of the platen mechanisms of Fig. 17, the view being taken substantially from the line 18-18 of Fig. 17;

Fig. 19 is a vertical sectional view of the platen mechanism of Fig. 18, the view being taken substantially along the line 19-19 of Fig. 18;

Fig. 20 is a view of the main pumps of the hydraulic platen actuating means, the view being taken substantially along the line 20-20 of Fig. 21;

Fig. 21 is a longitudinal sectional view of one of the main pumps of the hydraulic system, the view being taken along the line 21-21 of Fig. 20;

Fig. 22 is a cross sectional view of the pump actuating means, the view being taken substantially along the line 22-22 of Fig. 21;

Fig. 23 is a vertical sectional view of one of the make-up pumps of the hydraulic system;

Fig. 24 is a plan section taken substantially along the line 24-24 of Fig. 23;

Fig. 25 is a fragmental plan view of one of the platen mechanisms, as viewed from the line 25-25 in Fig. 17;

Fig. 26 is a fragmental vertical sectional view taken along the line 26-26 in Fig. 25; and

Fig. 27 is a fragmental vertical sectional view taken substantially along the line 27-27 in Fig. 26.

While I have shown in the drawings and will herein describe in detail certain preferred embodiments of my invention, it is to be understood that I do not thereby intend to limit the invention to the specific embodiments disclosed, but aim to cover all modifications and alternative constructions falling within the spirit and scope of the invention as expressed in the appended claims.

The platen mechanism of the present invention is illustrated herein in different embodiments which have a wide variety of different uses, and for purposes of disclosure these different forms of the invention have been herein shown as embodied in machines for producing complete business instruments, records and the like. Thus the

first form of the platen mechanism of the present invention is illustrated as embodied in the machine which is fully illustrated and described in my copending application, Serial No. 221,841, filed July 28, 1938, now issued as Patent No. 2,296,277, patented September 22, 1942. Reference may, of course, be had to my said copending application for details of structure and operation, and the present disclosure is accordingly confined to those elements of the machine which are most

directly related to the present platen mechanism. This machine, which is depicted in Figs. 1 and 2 of the drawings, is particularly adapted for the production of business instruments such, for example, as dividend checks S, Fig. 5. Such a dividend check includes constantly reoccurring data F, Fig. 5, which in the present instance is the name and location of the company issuing the check, the words "Check No.," the name of the bank on which the check is drawn, and kindred

data imparting characteristics to the check, including the border appearing thereon; changing data A, constituting an identification and characterizing the check and, in the present instance, this is an address comprising a name, street and number, and city and state; variable data V

which are the amount for which the check is to be payable; and other analogous data such as a date E, a number N and a signature B. The date, number and signature are the first data, in the machine as constructed, to be printed; next the variable data V are printed and thereafter the address A; and finally the form F are printed on the check.

The address or changing data A are printed on the check directly from a printing and control device such as the device D, Fig. 3, and the variable data V are printed under control of such a printing or like device. It is preferred to employ such printing and control devices for so to do eliminates the necessity of checking printing devices or the like against record cards or the like because the printing and control devices, such as are shown in Fig. 3, include both means from which an impression may be made directly and means under control of which impression or other operations may be performed. It is to be understood, however, that when reference is made hereinafter to a printing and control device, save in those instances where the avoidance of checking is essential, this term is to be considered generic for, as will be apparent to those skilled in the art, the platen mechanism of the present invention may be used with printing devices not equipped with control means. Hence in view of this it is to be understood that while the devices will be described as printing and control devices, this term is used in the generic sense hereinafter, particularly in those instances where it is not essential that the control means of such a printing and control device be employed.

The printing devices from which the printing impressions are made in such machines may take many different forms, but in most instances each printing device carries a plurality of lines of printing characters, such as embossed type, from which printing impressions may be made upon a sheet, business form or the like. While a wide variety of printing devices may be employed in machines of this character, the printing device disclosed in Mohler Patent No. 1,812,894 patented July 7, 1931, is typical of one form of printing device which may be employed. Another generally similar form of printing device adapted for use with the present invention is disclosed in Gollwitzer Patent No. 2,132,412 patented October 11, 1938. A printing device of this character includes a rectangular carrier or frame having an embossable metal printing plate removably retained in position thereon, type characters being embossed on such a plate to appear in relief on the operative face thereof. Type characters have also been embossed on a so-called one-piece printing device of the kind disclosed, for example, in Duncan Patent No. 1,026,246 patented May 14, 1912, and devices of this character may be utilized with this invention. Furthermore, in some instances type characters are formed on suitable stencil paper, carried by a frame of cardboard or other material, and suitable means are provided in printing machines through which such devices are fed to apply ink on the type characters and afford a printing impression on a sheet or the like and printing devices of this kind may be used with the present invention.

The printing and control device shown in Fig. 3 includes a carrier or, as it is called in the art, frame 1 having, in this instance, a metallic plate 2 removably retained thereon by fixed retaining devices 3, a bead 3' at the lower edge of the frame, and yieldable or depressible retaining

70
75

tongues 4. When one or the other of the tongues 4 is depressed the plate 2 may be slid endwise from the retaining devices 3 and the bead 3'. Type characters T are, in this instance, embossed in the metallic plate 2 so as to appear in relief on one face thereof and in intaglio on the opposite face, impressions being made from the relief faces of the type characters T when the printing and control device D is fed into printing relation with the platen P, Fig. 1, in the machine. The printing and control device shown in Fig. 3 also bears an identification card 5 on which an impression is made from the type characters T so that the data which may be printed from the type characters T may be read easily, this facilitating handling of the device D. This card 5 is removably retained on the frame 1 above the plate 2 thereon by suitable retaining devices 7 and a bead 8 at the top of the frame. A control card 6 is retained on the frame 1 at one side of the card 5 by the retaining devices 9 and the bead 8, a retaining device 7' being interposed between the cards 5 and 6, and the underlying portion of the frame 1 are adapted to have perforations formed therein in accordance with the code shown in Fig. 4 so as to afford control means or representations of data, and such perforations or control means are utilized in the production of the variable data V on the check S in the manner described in detail in my aforesaid copending application. The perforations in the control card 6 and the underlying portion of the frame 1 may be conveniently produced in a machine such as that disclosed in my co-pending application Serial No. 210,897, filed May 31, 1938, now issued as Patent No. 2,265,229, patented December 9, 1941.

While a complete description of the manner in which the card 6 and the underlying portion of the frame 1 are perforated is not essential to an understanding of the present invention it may be well to note that when data represented by perforations in the card 6 need be changed all that need be done is to remove this card 6 and substitute another unperforated card therefor and this new unperforated card may then be perforated to afford representations of the data that are to be substituted for that which has been previously incorporated in the device D. It may be that in so doing the frame 1 will also be perforated and this will be done in all instances where the newly formed perforations are located differently than the supplanted perforations, the supplanted and used perforations, in such instances, being covered and rendered ineffective by unperforated portions on the new card 6.

In Fig. 6 of the drawings a fragment of a proof sheet S-2 that may be produced in the machine is illustrated, and the characteristics of this proof sheet and the means in which it is produced will be explained more fully hereinafter to the extent necessary for a complete understanding of the present invention. It may be here pointed out however, that in the production of the proof sheet S-2 a pager and proofer such as that shown in my copending application, Serial No. 320,778, filed February 20, 1940, may be associated with the machine shown in Figs. 1 and 2.

The dividend check or sheet S is, in the present instance, severed from a web W, Figs. 1 and 2, that is withdrawn from a roll R which is rotatably supported in the stand 10, which, in the machine as shown in Fig. 1, is provided at the right-hand end of the machine. The web W is led from the roll R to a suitable web withdrawing device contained within the housing 11, Fig.

2, and during passage of the web through these devices the date E and signature B are printed thereon. Subsequently a portion of the web bearing these impressions is extended beyond a severing means including a knife 89 and thereupon the check or sheet S is severed from the web to be deposited in the sheet guideway G, which, as shown in Fig. 2, is provided longitudinally along the top 16 of the machine frame 15. The sheets S thus severed from the web are fed along the guideway G to the left in Fig. 2 by suitable sheet advancing means such as driven rollers 165 so that the leading edges of such sheets S are advanced into engagement with stop fingers 191 and 211. During the time that the leading edge of a sheet S is engaged with the stop finger 191, printing means included in a multiplying mechanism M, and which include a platen means 250, are operative to print variable data, as V, Fig. 5, on the sheet, and after such an impression has been made the stop finger 191 is retracted from engagement with the leading edge of the sheet which thereupon advances into engagement with the stop finger 211. When thus engaged with the stop finger 211, the sheet S is disposed beneath a platen P which at predetermined times in the course of operation of the machine is operated to make a printing impression on the sheet S directly from the type characters T of the printing and control device D from which the variable data V of this sheet was derived. The printing and control devices D are advanced through the machine in a step-by-step manner such that each device D comes to rest on an anvil located beneath the platen P so that when the platen P is moved toward a printing and control device resting on such anvil a printing impression is made on the sheet from printing characters embossed or otherwise formed on the device. Where the type characters on the printing and control device are formed by embossing, such printing impression is made through the intermediary of an inked ribbon interposed between the embossed type characters and the portions of the sheet upon which the printing impression is to be made. After an impression has been made on a sheet by the platen P the stop finger 211 is retracted from engagement with the leading edge of a sheet S which thereupon passes along the guideway G to the left in Fig. 2 through a form printing unit U by means of which the form impressions F are made upon the sheet so as to produce the complete document or business instrument. After the passage of the sheets through the form printing unit U, they are usually collected in a suitable sheet collector (not shown).

At the start of operation of the machine a supply of printing and control devices D are introduced into the magazine H from which the devices are withdrawn one at a time to be passed through the machine into detecting and printing positions therein. After passing through these positions the printing and control devices pass into mechanism which operates to direct the devices into one or the other of the drawers J, Fig. 1, in which such devices are stored when not in use and from which they are removed when they are introduced into the magazine H. In the machine in which the present invention has been illustrated the lowermost printing and control device D in the magazine H is removed therefrom and is fed forwardly through positions or stations in the printing device guideway. One of these stations constitutes a sensing station II,

Fig. 7, at which the control areas on the printing and control devices are sensed to effect set-up of the multiplying mechanism M, and another of which stations constitutes a printing station III, Fig. 7, wherein the printing devices come to rest on an anvil 264 and impressions are made directly from the type characters provided on the printing and control devices.

In the course of operation of the machine the desired feeding movement is imparted in a step by step manner to the printing and control devices D in a manner fully described in my aforesaid copending application Serial No. 221,841 filed July 28, 1938, there being an actuating mechanism 280 (Fig. 2) which for each desired feeding movement imparts a reciprocatory stroke to suitable carrier bars or other means mounted in the printing device guideway.

When the printing and control devices D are moved to station III, in the desired printing position above the anvil 264, impressions are made therefrom by the platen P, and this platen P may also make impressions from the other printing mechanisms such as a means for printing the number N on the sheet S, as explained in detail in my copending application Serial No. 221,841. In such an instance the additional impressions are made by printing mechanism which cooperates with an end portion such as the left hand end portion of the platen P as viewed in Fig. 12.

As has been explained above, the number of type characters that may appear on various printing and control devices may vary widely from device to device, and in order to prevent a heavy impression being made when only a few type characters appear on a printing and control device and a light impression being made when a large number of type characters appear, the present invention has provided a platen arrangement which will make uniform impressions even under conditions entailing extreme variations in the number of type characters.

One factor which contributes to the production of uneven impressions is spring, that is, twisting, in the member supporting the impression making member which, in the present instance, is the platen P. This may be overcome, to a substantial extent by employing relatively rigid members to support the impression making member such as the platen P and in the present instance a pair of relatively heavy and substantial side members 538 and 539, Figs. 7 and 12, are provided. The members are substantially U-shaped and are formed from relatively thick material. The U-shaped configuration of the side member 538 is afforded by substantially parallel arms 540 and 541, and an interconnecting arm 542, similar parallel arms 543 and 544, Fig. 12, and a similar interconnecting arm 545, constituting the side member 538.

The arms 540 and 543 are secured together by a tie rod 546, Fig. 7, a spacing sleeve 547 being disposed about this tie rod between these arms. The arms 541 and 544 are secured together by a tie rod 548, a spacing sleeve 549 being disposed about this tie rod intermediate these arms. A bar 550 extends between the arms 541 and 544 near the front ends thereof and the ends of this bar are rigidly connected to these arms. The foregoing arrangement of side members, tie rods, spacing sleeves and bar affords a rigid unitary structure which comprises the movable portion of the impression making means of which the platen P is a part.

It is well understood in the art to which printing machines of the kind to which this invention pertains find their principal use that it is essential that the face of an impression member such as the platen P be in strict parallelism with the face of a printing and control device bearing type characters from which an impression is to be made, this preventing smearing and kindred objectionable conditions in impression operations. This is best attained by providing the point of pivotatation of the movable part of the impression means in the plane in which the faces of the type characters from which impressions are to be made will lie and in the present machine this is accomplished by securing blocks 552 to the upper edges of the side plates 254 and 255 which form part of the machine frame and are shown in Figs. 7 and 12. V-shaped notches 554 are provided in the blocks 552 and the apices of these V-shaped notches lie in the aforesaid plane in which the type characters will lie when a printing and control device is disposed on the anvil 264.

Blocks 556 are secured to the arms 542 and 545 of the side members 538 and 539 and these blocks are formed to provide knife edges 558, which are seated in the V-shaped notches 554 so that these knife edges rest in the respective apices afforded by these V-shaped notches 554. Such mounting of the movable portion of the impression means enables this movable portion to be moved with minimum friction, and this arrangement insures that minimum wear will occur in the course of long use of the impression means. Furthermore, the seating of the knife edges 558 in the apices of the notches 554 assures that the point of pivotatation of the movable part of the impression means will lie in the plane above described.

While the rigid construction above described and the assurance that the face of the impression member will lie in the proper plane attribute to the production of the desired uniform impressions, this can be further assured by causing the impression pressure to be effected by a squeezing action which may be the result of the application of retroactive forces and in order to accomplish this I resort to a hydraulic system for applying the impression pressure.

It has been stated heretofore that the printing and control devices rest on an anvil 264 during the time impressions are made therefrom by the platen P and in order to realize the above referred to squeezing and the utilization of the retroactive forces when a hydraulic system is employed, I form a cylinder 559, Fig. 7, in the underside of the anvil 264, a piston 560 being reciprocal in this cylinder and having the rounded outer end thereof positioned to bear upon the bar 550 extended between the arms 541 and 544 of the side members 538 and 539. Thus when hydraulic pressure is impressed on the piston 560 this pressure is effective on the bar 550 to pivot the side members 538 and 539 about the knife edge pivotal supports thereof, and the force effective on the piston is also effective on the anvil and in this way the pressure incident to the impression making operation is a utilization of retroactive forces.

Hydraulic pressure is impressed upon the piston from a pump, generally indicated by 561 in Figs. 1 and 7, which includes an outer casing 562 welded or otherwise suitably secured to a bracket 563 that is pivotally mounted on a tie rod 239, Figs. 1 and 7, intermediate sections of the spacing sleeve 354, the positioning of this bracket intermediate these sections of the sleeve preventing longitudi-

dinal movement of the bracket 563 along the tie rod 239. An arm 564 depends from the bracket 563 near the end thereof and an adjusting bolt 565 is mounted in the lower end of the arm 564 and engages a flange on the upright 259 to limit pivotal movement of the bracket about the tie rod 239, this adjusting bolt enabling the outer casing 562 of the pump 561 to be adjusted into a proper vertical position.

The outer casing 562 of the pump 561 affords a guide for a piston 566 which is bifurcated, as indicated at 567, at its upper end, and a roller 568 is rotatably mounted on the shaft 569 in this bifurcation. A shaft 570 is journaled in suitable bearings, Figs. 7 and 9, provided at the upper end of the casing 562 and has a cam 571 fast thereon in alignment with the roller 568, the configuration of this cam being such that in each revolution of the shaft 570 the piston 566 is reciprocated in the outer casing 562, retroactive force being applied on the piston 566 to maintain the roller 568 in engagement with the cam 571 by a spring 572 mounted in a relieved part of the piston in the outer casing 562, this spring extending to a shoulder 573 formed on the outer edge of the cylinder 574, that portion of this cylinder immediately below the shoulder 573 being screw-threaded into the lower end of the casing, as indicated at 575. The head of the cylinder 574 is afforded by a block 576 that is bolted to the cylinder and which has a port 577 therein, the outer tube 578 communicating with this port 577. The outlet tube 578 leads to a port 581 provided in a block 582 secured to the rear side of the casting 263 which includes the anvil 264. The port 581 leads to a passage 583 in the block 582 which leads to the inlet port 584 that opens into the cylinder 559 above the piston 560 therein.

The part of the cylinder 574 that is cut away to define the shoulder 573 and the cut-away part on the piston defining a space to receive the spring 572 cooperate to afford a storage chamber or reservoir 579 which communicates with that portion of the cylinder 574 in which the lower end of the piston 566 is reciprocal through ports 580. The purpose of the reservoir 579 is to enable a greater quantity of a suitable hydraulic oil to be introduced into the system including the cylinder 574, port 577, tube 578, passage 583, port 584 and the area in the cylinder 559 above the piston 560, communication of this system with the reservoir 579 being established with the reservoir 579 through the ports 580. The additional supply of hydraulic liquid or oil in the reservoir 579 is sufficient to eliminate the necessity of replenishing the supply of hydraulic oil in the above described system except at infrequent intervals.

When the cam 571 engages the roller 568 and the piston 566 is forced downwardly this piston quickly moves from its normal at rest position shown in Fig. 7 and in the very first stages of this movement closes the ports 580, thereby trapping in the above described system a quantity of hydraulic oil sufficient to entirely fill this system and consequently as the piston 566 continues its downward movement the pressure impressed on the oil by the piston 566 is impressed on the piston 560, the difference in the diameter of the cylinders 574 and 559 and the difference in stroke of the pistons 566 and 560 affording a hydraulic lever which causes the piston 560 to exert substantial pressure on the bar 550.

The platen P is adjustably mounted at the free ends of the arms 540 and 543, this adjustable mounting being described in further detail

hereinafter, and when pressure is applied on the piston 560 the platen P is forcibly urged toward a printing and control device D supported on the anvil 264 to have an impression made onto a sheet S lying above the inked ribbon IRb that passes over the printing and control device resting on the anvil. It will be apparent that if a sheet does not overlie the inked ribbon IRb an offset will be produced on the face of the platen P, and this is objectionable as is well understood in the art. Therefore a detector is provided in association with the platen P which actuates mechanisms that cause the movement of the platen P toward a printing and control device on the anvil 264 to be interrupted in event no sheet overlies the ribbon IRb whereby the formation of an offset on the face of the platen in the absence of a sheet is avoided. There are instances, however, where the platen P is to make an impression operation even though no sheet as S is positioned therebelow. Hence, the means under control of the aforesaid detector are arranged to be operative only when, in an impression operation of the platen, a sheet as S should be disposed therebelow.

This detector in the present instance includes a spring-pressed pin 585 (Figs. 7 and 12) mounted in the plate 586 of the platen structure out of alignment with the inked ribbon IRb but in a position to be aligned with a sheet which should overlie this inked ribbon. An opening 587, Fig. 12, is provided in the bed plate 108 in alignment with the pin 585, and when the platen P moves downwardly the pin 585 moves toward the opening 587. If a sheet overlies the opening 587 the pin 585 is prevented from moving thereinto and in the course of downward movement the pin merely compresses the spring effective thereon. If, however, a sheet does not overlie the opening 587 then the pin 585 passes thereinto and engages a block 588 of insulating material on the upper blade 589 of a pair of switch blades, the other blade of which is indicated by 590, these switch blades being mounted on blocks 591 of insulating material in spaced apart relation and being supported on the underside of the bed plate 108. When, therefore, the pin 585 engages the block 588, contacts on the blades 589 and 590 are engaged to close an electric circuit which includes the solenoid 592, Fig. 7, provided a sheet as S should be below the platen P at this time, circuit to the solenoid 592 being open at a point other than the contacts on the blades 589 and 590 when an impression operation of the platen is not to be effective on a sheet as S. Such circuit arrangement is described in full detail hereinafter.

Energization of the solenoid 592 retracts the core 591 thereof, Fig. 7, to withdraw the pin 585 on this core from alignment with the end of the piston 599 reciprocally mounted in a cylinder 600 in the block 582, a spring 601 normally acting on this piston 599 to urge it into the position in which it is illustrated in Fig. 7 where it can be engaged by the pin 582 to be retained in the said position. The piston 599 is relieved as indicated at 602 to afford a passage through which communication is normally established between the ports 581 and 583. Thus the passage 602 and therefore, in effect, the piston 599 are part of the above described hydraulic system. Now when the solenoid 592 is energized by the engagement of contacts on the blades 589 and 590 and the pin 585 is retracted from engagement with the end of the cylinder 600, the hydraulic pressure being

applied on the piston 599 at this time will overcome the effect of the spring 601 and will force the piston 599 through the cylinder 600, to the right as viewed in Fig. 7. Such movement of the piston 599 through the cylinder 600 increases the capacity of the above described hydraulic system in such a way that the pressure impressed by the piston 599 is rendered ineffective to bring the platen P into a position whereat it would be effective to make an impression from a printing and control device on the anvil 264 below the inked ribbon IRb. The piston 599 can only move through the cylinder 600 to relieve this pressure in those instances where the presence of a sheet above the ribbon IRb does not prevent the pin 585 from passing into the opening 587 and hence the above described arrangement constitutes a safety which prevents the formation of offsets on the face of the platen P.

It has been explained heretofore that it is desirable that the platen P make uniform impressions irrespective of the number of type characters provided on the various printing and control devices moving into the printing and control position below the ribbon IRb, and it has been explained that this in a great measure is attained by utilizing retroactive forces which are effective to apply printing pressure on the platen P. This is realized in the present instance by providing the cylinder 559 in the anvil casting 263 directly below the anvil and by applying the platen P pressure directly above the anvil so that the force resisting the piston 560, which applies the platen pressure, is impressed on the anvil 264 and this force is opposite to or retroactive with respect to the force imparted through the platen P. This arrangement results in a printing operation entailing what is, in effect, a squeezing action.

It has also been explained that by avoiding a rigid structure for supporting the platen P those difficulties attendant to springing in such a structure are reduced to a minimum and since such a structure is utilized in the present machine the production of uniform impressions is additionally assured.

To further insure that uniform impressions will be made in various printing operations of the platen P, I stop the platen P in an identical position with respect to a printing and control device 50 on the anvil 264 in each impression making operation. To this end the lower arms 541 and 544, Figs. 7, 14 and 15, are so arranged that their outer ends extend above the girder 261. When the platen is in an upper or inoperative position, in 55 which it is shown in Fig. 14, the arms 541 and 544 are free of the upper edge of the girder 261, but when the platen P attains its operative or impression making position, in which it is shown in Fig. 15, the arms 541 and 544 engage and rest 60 upon the upper edge of the girder 261. The parts are so arranged that at the time the arms 541 and 544 so engage the girder 261, the platen P will be in parallel relation with respect to the surfaces of type characters on a printing and 65 control device supported by the anvil 264 and at the time this parallel relation is attained the face of the platen P will be in impression making relation with such type characters. It will be manifest that the engagement of the arms 541 and 70 544 with the girder 261 at this time effectively prevents the platen from moving beyond the above described parallel relation with the type characters and this further insures that uniform impressions will be produced by the platen P in 75 various impression making operations thereof.

It is essential that means be provided to insure that the platen remain in its upper or inoperative position shown in Figs. 7 and 14, except during a printing operation thereof and to this end blocks as 603 are secured to and extend beyond the free ends of the arms 541 and 544, a rod 604 extending between and being supported by these blocks. One end of a spring 605, Fig. 7, is fast to this rod, the opposite end of this spring being connected to a spring anchor 606 fast in the cylinder 559, and this spring 605 serves to effectively retain the platen in its upper inoperative position until pressure is applied through the above described hydraulic system.

The shaft 570 on which the cam 571 is mounted makes one complete revolution each time the platen P is to be operated to produce an impression, and to this end a pulley 607, Figs. 1, 7 and 9, is rotatably mounted on this shaft, a belt 608 being passed about this pulley and a pulley 609, Fig. 1, fast on the main drive shaft 19 which during operation of the machine is continuously driven by a belt connection 20 from a drive motor 21. Thus so long as the main drive shaft 19 is rotating the pulley 607 is rotated. The pulley 607 includes a hub provided with clutch teeth 610, Figs. 9 and 10, which are adapted to cooperate with clutch teeth 611 on a sleeve 612 slidably but non-rotatably mounted on the shaft 570, this sleeve normally being acted on by springs 613 to urge the clutch teeth 611 toward the clutch teeth 610, these springs reacting against a collar 614 fast on the shaft 570. The clutch, including the clutch teeth 610 and 611, is of the kind that has been described above and which, as has been stated, is disclosed in my co-pending application, Serial No. 179,348, filed December 11, 1937.

A pin 615 is fast in the sleeve 612 and is engageable with a cam surface on the arm 616 that is pivotally mounted on a stud 617 carried by the bracket 552, Fig. 6. An arm 618 on the core 619 of the solenoid 620 has a lug 621 thereon that is engageable with the free end of the arm 616 and when the solenoid 620 is energized this lug acts on the arm 616 to retract the cam surface thereon from engagement with the pin 615 whereupon the springs 613 engage the clutch teeth 611 with the clutch teeth 610 and thereupon the shaft 570 starts to rotate with the pulley 607. Shortly after such operation is initiated, the pin 615 engages the arm 618 and disengages the lug 621 from the arm 616 which thereupon returns to a position such that near the end of a rotation of the shaft 570 the pin 615 will ride over the cam surface on the arm 616 and thereupon disengage the clutch teeth 611 from the clutch teeth 610 so as to interrupt operation of the shaft 570 at the end of a complete revolution thereof. In a manner described hereinafter the solenoid 620 is energized each time an impression operation is to be made by or through the medium of the platen P and hence the cam 571 causes the piston 566 to be reciprocated each time an impression operation is to be made.

In those instances where the piston 599, Fig. 7, moves through the cylinder 600 to, in effect, enlarge the capacity of the hydraulic system, which occurs upon energization of the solenoid 592 in the manner above described, the cam 571 of the pump 561 of course makes a complete revolution and in the course of the operation of the hydraulic system induced by such rotation of the cam 571 the spring 605 returns the platen to its upper inoperative position shown in Fig. 10, and when the cam 571 comes to rest in its normal at

rest position, Fig. 7, the hydraulic system is relieved of pressure whereupon the spring 605 becomes effective to return the relief piston 599 to its normal position in the cylinder 600, which position is shown in Fig. 7. Shortly after the spring 605 starts to return the platen to its upper inoperative position the switch actuating pin 585 is disengaged from the block 588 and thereupon the associated switch is opened so that circuit to the solenoid 592 is opened. It will be understood that a spring is always effective on the core 597 of the solenoid 592, the effect of this spring being overcome when the solenoid is energized. Thus at the time circuit to the solenoid 592 is opened the spring effective on the core 597 is urging the core and the pin 598 thereon upwardly, and hence at the time the spring 605 returns the piston 599 to its normal position shown in Fig. 7, the pin 598 moves into a position behind the piston 599 to thereby prevent movement thereof through the cylinder 600. Therefore until the solenoid 592 is again energized the capacity of the hydraulic system is such that each time the cam 571 makes a complete revolution a complete impression operation is made by the platen P, such complete operation only being prevented in event of the absence of a sheet which causes the contacts on the blades 589 and 590 to be engaged in the manner above described to energize the solenoid 592.

In order to insure that a complete impression operation of the platen P will be made each time this should properly occur, the capacity of the pump, generally indicated by 561, is greater than the capacity of the area above the piston 560 in the cylinder 559, and to care for such excess capacity pressure relief means are provided so that pressure effective on the piston 560 will be relieved once the arms 541 and 544 have engaged the girder 261. To this end a pressure relief valve, generally indicated by 622, Fig. 7, is provided in the block 576. This pressure relief valve controls communication between a port 623 that leads to the reservoir 579 and a port 624 communicating with the area in the cylinder 574 beyond the operative end of the piston 566. The valve member 625 of the valve 622 is acted on by a spring 626 and the effective force of this spring is so adjusted that the valve member 625 remains seated to close off communication between the ports 624 and 623 until such time as pressure in the hydraulic system should properly be relieved.

As is well understood in the art, it is essential that a hydraulic system be free of air in order to insure proper operation thereof and this is accomplished in the embodiment disclosed in Figs. 1 to 15 by providing means operative to bleed any accumulated air from the system, such means communicating with the highest point in the system which is where entrapped air will accumulate. A suitable bleeder arrangement may merely comprise a relatively long tube of small diameter, but in the present instance in order to avoid making provision to accommodate such a long tube I utilize a metering device to control bleeding of air from the hydraulic system. This metering device is arranged to afford sufficient friction to resist appreciable escape of hydraulic oil from the system so that the effective pressure in the system will not be relieved. However, a device which is effective to apply this degree of friction to hydraulic oil will not necessarily apply impeding friction to the escape of 75 air.

Thus I provide a port 621, Figs. 7, 14, and 15, at the highest point in the hydraulic system, which in this instance will be at the top of the cylinder 559. A tube 628 leads from this port 621 to the inlet chamber 629 of a metering device, generally indicated by 630, Figs. 7 and 8. A metering orifice 631 of predetermined diameter establishes communication between the inlet chamber 629 and the outlet chamber 632 of the metering device 630, and a pin 633 of accurate diameter is arranged in the accurately sized orifice 631. The sizes of the orifices 631 and pin 633 are such that sufficient friction will be afforded to resist the flow of oil through the orifice to such a degree that the oil, even when pressure is applied thereto, will only slowly bleed through this orifice, this slow leakage being of such a degree that the oil will drip into the outlet chamber 632. However, this sizing of the orifice 631 and pin 633 and the resulting friction accruing from such sizing is not such that it will impede the flow of air and therefore any air which may accumulate at the high point in the system, namely, in the cylinder 559, is quickly bled therefrom as soon as the piston 566 acts to apply hydraulic pressure in the cylinder 559. Air bled from the cylinder 559 into the chamber 632, and any oil leaking thereinto, are directed through a tube 634 back to the reservoir 574, this tube interconnecting this chamber and this reservoir. The reservoir 574 communicates with the atmosphere through a port 574', Fig. 7, and air bled to the reservoir escapes through this port to the atmosphere.

It has been explained that in order to attain uniform impressions it is necessary that the face of the platen P be in parallel relation with the faces of type characters on a printing device D resting on the anvil 264. To insure such parallel relation the platen P is adjustably mounted in position, as has been stated hereinabove. The impression face of the platen P is afforded by a rubber block 635 fast, in the present instance, in a metal block 636 which has a dovetail groove 637 in the upper face thereof that is slidable onto a dovetail strip 638 secured to the underside of the plate 586. The plate 586 is connected to and carried by a block 639 which in turn is connected to and carried by a block 640. The block 640 is disposed between and firmly connected to the lower edges of the outer free ends of the arms 540 and 543 of the side members 538 and 539 of the platen structure. The block 639 is connected to the block 640 by an attaching screw 641 which, as best shown in Fig. 7, passes through the block 640 at a medial point therein, this screw being freely passed through the block 640 and being screw-threaded into the block 639. At points corresponding to the corners of a rectangle disposed about the attaching screw 641, adjusting screws 642 are threaded through the upper face of the block 639, and by adjusting the position of these screws 642 the impression face 632 of the platen P may be brought into the above described parallel relation with the face of type characters T on a printing and control device D resting on the anvil 264.

In the machine shown in Figs. 1 and 2, a portion of the printed matter on a proof sheet is printed from the printing and control devices D through the use of the same platen P which is used in making printing impressions from the printing and control devices onto the sheets S, and to attain this purpose a proof sheet, in the form of a web 901-W, Fig. 7, is passed between the plate 586 and block 639 as described more

fully in my copending application, Serial No. 320,778, filed February 20, 1940. In order to provide a space through which such a proof sheet may pass the plate 586 is connected to the block 639 by four screws as 643, Fig. 13, which freely pass through the block 639, but which are screw-threaded into the plate 586. Sockets 644 are formed in the under face of the block 639 to receive springs 645 that are disposed about the screws 643, these springs seating against the bottom of the socket 644 and the upper face of the plate 586 and normally forcing the plate 586 away from the block 639. When the face 635 of the platen P attains printing position and starts to make an impression the plate 586 moves toward the adjacent face of the block 639 and compresses the springs 645, wherefore a proof sheet passing between these blocks is squeezed during the impression making operation, the thickness of this sheet being taken into consideration when the screws 642 are adjusted to dispose the impression making face 635 of the platen P in its above described parallel relation with the faces of type characters.

Mention has been made heretofore that the platen P not only makes impressions from printing and control devices which come to rest on the anvil 264 but that it also makes other impressions and in the present instance one of these other impressions is the printing of the number N on the checks or sheets S, and still other impressions are the printing of a corresponding number and other data on proof sheet, Fig. 6, which is formed by the web 901-W. These impressions are made from what will be called auxiliary printing mechanisms and it is to be understood that while in the present embodiment illustrated in Figs. 1 to 15, impressions are made from these auxiliary printing mechanisms by the platen P, which is the same platen as that which makes printing impressions from the printing and control devices D on the anvil 264, other platens could be provided, and the auxiliary printing mechanisms would in such instance be located at positions in the machine other than that at which such printing and control devices cooperate with the platen P in forming the impressions A on the sheets S. If the auxiliary printing mechanisms were located in positions other than that at which impressions are made therefrom by the same platen as that making impressions from the printing and control devices it will, of course, be understood that such positioning would produce other printing positions. However, it is convenient to employ the same platen to make impressions from both the auxiliary printing mechanisms and the printing and control devices and for this reason this arrangement is resorted to and is shown in Figs. 1 to 15 hereof. This arrangement enables the stop finger 211, Fig. 2, to be employed to position the sheets to dispose them in position to receive impressions from printing and control devices on the anvil 264 and also to receive impressions from the auxiliary printing mechanisms.

One such auxiliary printing mechanism, which, may cooperate with the platen P may constitute a numbering mechanism, which is not shown herein but which is described in detail in said copending application, Serial No. 221,841, filed July 28, 1938.

The type characters of such a numbering machine are disposed beneath the inked ribbon IRb and impressions are made from these type characters through the ribbon IRb by the platen P.

In the present instance, two impressions are made from the numbering machine in each setting thereof, since corresponding numbers are to be printed on the sheet S and the proof sheet S-2. The first of these impressions is made onto a sheet S to print the number N thereon and the second of these impressions is made on the proof sheet to print the same number N' thereon.

Another such auxiliary printing mechanism which may cooperate with the platen P may comprise means for printing on the proof sheet (in association with the number and the impression made from each device D) a further printing impression V', Fig. 6, which, in the present instance, corresponds to the variable or numerical data V printed on the sheets S. It is essential that the variable data thus printed on the proof sheet in association with a number printed thereon correspond to the variable or numerical data and which are printed on the correspondingly numbered sheet S by the multiplying mechanism M. This may be effected in a wide variety of ways and in the present instance this is accomplished by printing such variable data on the proof sheet 301-W by means set up under the control of the multiplying mechanism M. One means for attaining such a set-up is disclosed in detail in my aforesaid copending application, Serial No. 21,841, filed July 28, 1938, and in accordance with the disclosure therein made, the multiplying mechanism M operates through intermediate means such as a punch card system to set up an auxiliary printing mechanism generally indicated by 672, Fig. 1, which prints the corresponding variable or numerical data V' on the proof sheet.

The auxiliary printing mechanism 672 is in the nature of a variable printer and is of the character embodying shiftable type carriers. The set-up type are actuated, as by means of a hammer mechanism, so as to effect printing cooperation between the set-up type and the sheet. In such printing cooperation the platen P serves as a back-up member against which the sheet is pressed by the actuated type, and provision is therefore made for actuation of the platen P to 45 the position of Fig. 11 whenever a printing impression is to be made from the auxiliary printing mechanism such as the printing mechanism 672. It will be recognized that the actuation of the platen P for this purpose takes place at a time when no sheet S is located at printing position, since an impression is to be made simultaneously from the printing device D onto the proof sheet or web 301-W.

Since, in the absence of a sheet S at printing position, the detecting pin 585 closes switch 589-590 so as to disable the hydraulic platen actuating means, provision is made for initiating the cycle of the platen actuating means independently of the means which initiates such operation when a printing impression is to be made on a sheet S. Such independent control of the platen actuating means is attained through utilization of a shaft 702, Fig. 1, of the auxiliary printing mechanism 672, this shaft being operated through a single revolution in each cycle of operation of the auxiliary printing mechanism 672. It will be recognized that the auxiliary printing mechanism 672 is operated through a printing cycle only in alternate cycles of the machine, or in other words, when the data A', the number N' and the variable data V' are to be printed on the proof sheet or web. As shown in Fig. 1, the shaft 702 is driven from the main shaft 19 by a belt connection 763 and an intermediate one, revolu-

tion clutch 764, this clutch preferably being of the type shown in my copending application Serial No. 179,348, filed December 11, 1937. Thus the shaft 702 operates through a single revolution whenever the clutch 764 is engaged, and the desired control of the platen actuating means is attained by switch means and switch control means comprising a pin 898", Fig. 16, mounted on a cam or disk 899 fast on the shaft 702. In 10 the course of operation of the shaft 702, the pin 898" moves into engagement with a block 899' of insulating material on the blade 898' of a switch 897', and engages a contact on this blade with a contact on the blade 896' of the switch 897'. The switch 897', in the manner described hereinafter, is in circuit with the solenoid 620 so that each time the contacts on the blades 898' and 896' are engaged with each other circuit is closed to the solenoid 620 to effect an operation 15 of the platen P in the manner described hereinabove.

In the machine in which the present invention is illustrated, the various operative mechanisms in the machine while in most instances deriving power from a common source are not interconnected by gear interconnections. Instead of resorting to such a construction, each of the various operative mechanisms has an independent control for connecting the operative portions in the mechanism with the source of power and in this connection it should be noted that if so desired a separate source of power could be provided for each and every one of the various operative mechanisms in the machine, the utilization of a main drive shaft such as the main drive shaft 19 merely being an expeditious way of affording a source of power. Since, in this machine, the various operative mechanisms receive power through suitable controls, and more specifically clutches, provided in each of the mechanisms and since these clutches are electrically controlled, by means of solenoids, it is possible to associate the regulating means for the controls or clutches of the mechanisms to be timed relative to the printing unit U directly with the form printing unit U, these regulating means being in the form of switches for controlling circuit to the solenoids of the clutches. To this end a shaft 1078, Fig. 2, is journaled in suitable bearings provided on the outer face of the form printing unit U. This shaft is constantly rotated during operation of the machine by means including a belt connection 1077, Fig. 1, driven from the main drive shaft 19.

55 A plurality of cam disks, including a cam disk 1083, are fast on the shaft 1078 to be rotatable therewith, and these cam disks, as will be explained in further detail hereinafter, operate the switches that control operation of various operative mechanisms in the machine.

In the present instance where the machine is set for duplicate work as has been explained hereinabove, the drive ratio for the cam shaft 1078 and the cycle of the form printing unit is one-to-two, so that the shaft 1078 and the various disks fast thereon make one revolution for each two revolutions of the operative parts or impression forming means of the form printing unit. In this relation, however, it should be observed that the form printing unit is in effect idle in alternate revolutions of its drum 1043, since during such revolutions there is no sheet S fed thereto and the machine functions solely in printing the proof sheet S-2.

In the course of an automatic operation of the

Machine in which a sheet S is to be produced, the operation of the platen P is controlled by the cam 1083. Thus the solenoid 620 of the hydraulic platen actuating means is energized by closure of the switch 1685 (Fig. 16) and this is effected by engagement of the lobe on the cam 1083 with a switch blade 1687 whereupon a contact on this blade is engaged with a contact on the blade 1688 and thereupon circuit is closed from the line wire 526 through conductor 1690, switch 1685 and conductor 1692 to conductor 1683, winding of solenoid 620, and conductor 1684 to line wire 527.

Where the machine is set for duplicate work, such control of the platen by the cam 1083 takes place in alternate machine cycles, and in the other or intermediate machine cycles, during which the auxiliary printer is in operation, the platen is governed by the auxiliary printer. In such machine cycles the pin 898", Fig. 16, engages a contact on the blade 899' with a contact on the blade 896' and thereupon circuit is closed from line wire 526 through conductor 1693, switch 897', conductor 1694 to terminal 1691 and thence through conductor 1689, terminal 1682, conductor 1683, winding of solenoid 620, and conductor 1684 to line wire 527.

When the solenoid 620 is energized by closure of the switch 1685, the resulting operation of the platen P is to make an impression on a sheet S, but when the solenoid 620 is energized by closure of the switch 897' an impression is to be made on the proof sheet or web 901—W. It will be recalled that a pin 585 is associated with the platen P so that, in the course of downward movement of the platen P, if a sheet S does not lie therebelow, this pin engages a block 588 of insulating material on a blade 589 to engage a contact on this blade with a contact on the blade 590 to thereby close circuit to the solenoid 592 to retract a pin 598 on the core 597 of this solenoid from alignment with a plunger 599 whereby capacity of the hydraulic system, which applies pressure on the platen P, is increased in such degree that printing pressure is not applied by the platen. It will be recognized, however, that when an impression operation is made by the platen P on the web 901—W a sheet S will not lie beneath the platen P and that therefore the pin 585 will act to engage contacts on the blades 589 and 590. In this instance however circuit to the solenoid 592 is not to be closed because so to do would prevent the platen P from making an impression on the web 901—W.

In view of the foregoing circuit is established through the blades 589 and 590 only when an impression is to be made on a sheet as S so that if the pin 585 engages the contacts on these blades in any other impression operation of the platen P the solenoid 592 will not be energized to increase the capacity of the hydraulic system and prevent a printing operation of the platen P. The manner in which this is accomplished can best be ascertained by reference to the wiring diagram, Fig. 16, and it is as follows:

The switch 1685, Fig. 16, includes a third blade 1686 and when the cam 1083 acts to engage contacts on the blades 1687 and 1688 to close circuit to the solenoid 620 circuit is also closed from the line wire 526 through conductor 1690, the contacts on the blades 1688 and 1687 to a contact on the blade 1686 and thence through a conductor 596 to the blade 589. The dwell on the cam 1083 is of sufficient length that it maintains the various contacts on the blades of the switch

1685 engaged until after the platen P should have made an impression from a printing and control device D on the anvil 264 and hence, if the pin 585 engages the contacts on the blades 589 and 590, when circuit is closed to blade 589, as just described, then circuit is closed from the blade 590 through a conductor 594, the winding of the solenoid 592 and a conductor 593 to the line wire 527. Thereupon in the manner above described the capacity of the hydraulic system is increased and the platen P is prevented from making an impression, it being understood that the pin 585 engages the contacts on the blades 589 and 590 and the solenoid 592 energizes prior to the time the platen P has attained impression making position with respect to the printing and control device on the anvil 264. It will of course be understood that if two impressions were to be made on a sheet as S then both of the two lobes that would be provided on the cam 1083 in this instance would be sufficiently prolonged to enable the just described operation of the solenoid 592.

Figs. 17 to 24 of the drawings disclose a somewhat different machine for producing business instruments, and in this machine independent platen mechanisms are provided for the production of the sheets S and the proof sheets S—2 as contrasted with the use of but a single platen for the production of both sheets in the machine shown in Figs. 1 to 16; and in addition, a somewhat different form of hydraulic platen actuating means is employed in the machine shown in Figs. 17 to 24. Thus the printing or printing and control devices D are in this instance fed one by one from the magazine H along a printing device guideway 1700 so as to come to rest successively at a plurality of different positions or stations of which two stations constitute printing positions. The printing device guideway 1700 is formed by means including spaced supporting and guiding rails 1701 and 1702 which extend in the present instance from front to rear of the machine and are carried by a machine frame designated generally as 1703. In such advancing movement along the guideway 1700 each printing device comes to rest successively at a sensing station II, a first printing station III, and intermediate station IV, and a second printing station V, after which the printing device is discharged downwardly at 1704 to a suitable collecting means.

At the first printing station III the printing device may be utilized in producing a business instrument such as the check S, there being a suitable guideway G', similar to the guideway G, along which a sheet S may be moved into printing position III beneath a platen P—2. When a sheet S is thus positioned, it is located directly over an inked ribbon IRb, and the printing device D is located beneath the inked ribbon and on top of an anvil 1705 which is supported between the two rails 1701 and 1702. Through actuation of the platen P—2, in a manner to be hereinafter described, a printing impression may be made from the printing device onto the sheet S so as to provide the identification data A thereon. Other means are provided in the machine for printing the variable data V, the number N, the signature B and the form F, and since the particular means employed in printing the signature and the form do not constitute a part of the present invention, a specific description thereof will not be incorporated herein. It will be observed, however, in Figs. 25, 26 and 27 of the drawings, that a platen mechanism PM is pro-

vided adjacent to the platen mechanism P, and this platen mechanism PM is utilized in printing the variable data V and the number N on the sheet S, as will be hereinafter described. The variable data V is, in the present instance, printed under the control of a multiplying mechanism, as M which, as described in my copending application, Serial No. 416,749 filed October 27, 1941, controls the setting of type segments 1706 of the variable printer VP disposed beneath the platen PM. The multiplying mechanism as M is controlled by the perforations in the control card 6 of a printing and control device D sensed at sensing station II.

After a printing device D has come to rest at station III for the performance of a printing operation therefrom, it is advanced through the idle station IV and thence to the second printing station V and at this station a proof sheet is prepared. As hereinbefore pointed out the proof sheet is prepared through printing upon a web such as the web 901—W, and this web is led across the printing station V about stationarily mounted guide rollers 1707 and 1708 to thereby guide the lower run of the web under a platen mechanism P—3 and thence upwardly and then forwardly over the platen mechanism P—3 in spaced relation thereto. The platen mechanism P—3 is arranged to cooperate with an anvil 1715 which is located between the two rails 1701 and 1702 so as to be supported at least in part by the two rails.

The two platens P—2 and P—3 are arranged for independent actuation through hydraulic actuating means, and to this end the anvils 1705 and 1715 embody hydraulically actuated piston and cylinder device which are operated through the medium of individually operable pumps 1720A and 1720B. The pumps 1720A and 1720B are similar in form and construction, and are capable of independent actuation from a common power source as will hereinafter be described.

The platen P—2 is generally similar in form and construction to the platen P embodied in the machine shown in Figs. 1 to 16, and similar reference numerals have been employed for corresponding parts. It will be observed that the platen P—2 has a pair of U-shaped supporting frame members which are spaced by generally similar spacing sleeves and tie-rods, and a similar knife edge mounting is provided therefor. The platen P—2, however, is arranged so that the forwardly projecting ends of the lower arms, as the arm 544, are limited in their downward movement through engagement with a cross bar 1725 which is secured as by bolts upon the downwardly extending flanged edge 1726 of the anvil 1705. It will also be observed that the detecting means which includes the finger 585 has been eliminated in the platen P—2, and since the platen P—2 is not utilized to print a number such as the number N' or variable data such as V' upon a proof sheet, the length of the platen face member 635 in a direction longitudinally of the guideway G' may be substantially reduced.

The actuating or impression forming movement of the platen P—2 is obtained through the medium of a piston 560' mounted in a vertical extending cylinder 559' formed in the anvil 1705, and when hydraulic liquid under pressure is introduced through a passage 1727 into the upper end of the cylinder 559', the piston 560' is forced downwardly in the cylinder 559' so as to bear against an adjustable abutment 1721 provided in a cross bar 550' which extends between the two

lower arms of the platen supporting frame. It will be observed that the hydraulic liquid under pressure is supplied through a pipe 1730, and the passage 1727 is continuous from the pipe 1730 to the upper end of the cylinder 559'. Thus the relief chamber which was controlled by the solenoid 592 of the machine shown in Figs. 1 to 16 has been eliminated in the actuating mechanism for the platen P—2. When the pressure of the hydraulic liquid in the cylinder 559' is released, the platen P—2 is returned to its elevated position by one or more springs 605' connected between the cross member 545' and the machine frame 1703.

15 The platen mechanism P—3 is best shown in Figs. 17, 18, and 19 wherein it will be observed that the platen mechanism P—3 embodies a U-shaped supporting and actuating frame 1735 which is in a broad sense similar to the U-shaped

20 frame provided for the platen mechanism P—2. The frame 1735, however, has but a single U-shaped member which has an upper arm 1736, a cross member 1737 and a lower arm 1738. As shown in Figs. 18 and 19, the connecting or cross

25 member 1737 has oppositely projecting mounting mounting arms 1739 and 1740 at the ends of which aligned knife edge bearing members 1741 and 1742 are mounted. The knife edge bearing members 1741 and 1742 are arranged to rest in V-shaped bearing notches such as the slot 1743 shown in Fig. 19. The bearing notches 1743 are formed in the side members 1744 of a relatively rigid supporting frame which is secured by bolts 1745 to the rail 1702.

30 35 The frame 1735 is urged in a clockwise direction toward an inactive or platen retracting position by means of a pair of springs 1746, the lower ends of the springs 1746 being connected to an anchoring rod 1747 while the upper ends thereof are connected to anchoring pins 1748 which are mounted in the connecting portion 1737 of the frame 1735 so as to project therefrom in a direction opposite from the arms 1736 and 1738 thereof.

40 45 The platen supporting frame 1735 is actuated by hydraulic means which includes a vertically extending cylinder 1750 formed in the anvil 1715, and a piston 1751 which is reciprocal in the cylinder 1750. The lower end of the cylinder 1750 is open so that a bearing head 1752 on the lower end of the piston may bear against an adjustable stop member in the form of a screw 1753 mounted in the lower arm 1738. When hydraulic liquid under pressure is supplied to the upper

50 55 end of the cylinder 1750 through a passage 1755, Fig. 17, the piston 1751 is forced downwardly until an abutment surface 1756 on the arm 1738 engages an abutment surface 1757 formed on a stationary plate 1758, and such limitation of a movement of the platen supporting frame 1735 insures that the platen will in every instance produce uniform printing impressions regardless of the variations in the number of printing characters embodied in the printing devices D.

60 65 When the pressure of the hydraulic liquid is reduced at the end of a printing operation, the springs 1746 act to return the platens to their retracted or upper positions, and such retracting movement is in the present instance limited by stop means which is mounted on the upper end of the piston 1751. Thus as shown in Fig. 19 of the drawings, this stop means comprises a washer 1760 mounted beneath the head of a mounting screw 1761, the mounting screw extending through a spacing sleeve 1763 and being

70 75

threaded into the upper end of the piston 1751. The upper end of the cylinder 1750 is suitably recessed as the sleeve 1763 to provide clearance for the head of the screw 1761, and hence when the piston 1751 is forced upwardly, the head of the screw enters the recess 1763 until the washer 1760 is seated against the upper wall of the cylinder. In the present instance this structure is also utilized in securing a cup-washer 1765 in position on the top of the piston 1751, and this end is attained through the use of a clamping plate 1766 which is positioned within the cup-washer 1765 and beneath the lower end of the spacing sleeve 1762. Thus when the screw 1761 is tightened, the clamping plate 1766 is urged downwardly into the clamping relation with respect to the cup-washer 1765. With the stop means thus provided the piston 1751 is invariably located so that the upper edge of the cup-washer 1765 is located beneath the inlet opening of the cylinder 1750 to thereby provide for unrestricted and unobstructed entry of hydraulic liquid into the cylinder. In the present instance this inlet includes the vertical bore 1755 which intersects with a horizontal bore 1768, Fig. 17, and the bore 1768 is so located that it provides the clearance or recess 1763 for the head of the screw 1761. The bore 1768 is permanently closed at one end by a plug 1769, while an upwardly extending bleed opening is provided at the other end, this bleed opening being closed by a removable screw threaded plug 1770 which may be removed for the purpose of bleeding air from the hydraulic system. Similar stop structure and a similar bleed opening are also provided in connection with the piston and cylinder means of the platen P-2.

The platen mechanism P-3 is utilized in the production of proof sheets of the general character shown in Fig. 6 of the drawings, but the arrangement of the proof sheet in this instance is such that the variable data 'V' is printed in the middle column of the proof sheet while the number 'N' is printed in the third or right-hand column of the sheet. Thus as shown in Fig. 19 of the drawings, a variable printer 1780 is disposed just to the left of the anvil 1715, while a numbering mechanism 1781 is disposed just to the left of the variable printer.

Separate or individual platen sections are provided on the platen supporting frame 1735 for the formation of the identifying impressions A', the variable data impressions V', and the numbering impressions N'. Thus a platen section 1785 is disposed upon the arm 1736 for cooperation with a printing device located at printing position V over the anvil 1715; a platen section 1786 is mounted on the arm 1736 for cooperation with the variable printer 1780; while a platen section 1787 is disposed on the arm 1736 for cooperation with the numbering mechanism 1781. A single inked ribbon IRb-2 cooperates with all of the platen sections thus provided, and in the present instance this inked ribbon extends beneath and longitudinally of the arm 1736 so as to be positioned beneath all three platen sections. At its right hand end, as viewed in Fig. 19, the ribbon IRb-2 passes through a clearance slot 1739' formed in the mounting arms 1739 and 1741.

For the purpose of supporting the platen section 1786 a mounting plate 1788 is secured on the bottom of the arm 1736 adjacent the end thereof by means such as screws 1789. The mounting plate 1788 has a forwardly projecting and down-

wardly offset portion 1790 beneath which the platen section 1786 is mounted. Such mounting is in the present instance obtained by means of a pair of spaced leveling screws 1791 which extend downwardly through threaded openings in the plate 1790 so that the reduced lower ends rotatably engage suitable sockets formed in the upper face of platen section 1786. A headed screw 1792 extends downwardly through the mounting plate 1790 and is threaded into the platen section 1786 substantially midway between the two leveling screws, and by suitable adjustment of the screws 1791 and 1792 the platen section 1786 may be adjusted so that its lower or operative face will be located in the proper relation to the variable printer 1780 when the platen supporting frame 1735 has been actuated to its active position. The platen section 1786 serves merely as a backing member for the hammer-actuated type elements of the variable printer 1780, and hence a printing impression will not be made by the platen section 1786 as a result of the lowering of the platen unless the type elements of the variable printer are actuated by their hammer mechanism.

The platen section 1785 which is utilized for printing the identification data A' is arranged so that it may be shifted selectively between active and inactive positions; and provision is also made for leveling the lower or operative face of the platen section 1785 so as to assure proper cooperation thereof with the type characters of the printing devices. In accomplishing this result the platen section 1785 is supported beneath a platen mounting plate 1795 which is in turn supported beneath the arm 1736. The platen supporting plate 1795 is urged in an upward direction by means of a spring 1796 which is located in a recess 1797 in surrounding relation to a headed bolt 1798, and this bolt extends downwardly through the arm 1736 and the plate 1788 and is threaded into the mounting plate 1795. Thus the mounting plate 1795 is constantly urged in an upward direction and into contact with a plurality of laterally spaced leveling screws 1799 which extend downwardly through the projecting edge portions of the plate 1788 so as to bear upon the upper face of the mounting plate 1795. The mounting plate 1795 may therefore be leveled through appropriate manipulation of the screws 1799, and the adjusted relation is maintained by retaining springs 1800 which bear against the sides of the heads of the leveling screws 1799.

The platen section 1785 is supported beneath the mounting plate 1795 upon a plurality of headed screws 1801 which are located in sockets formed in the mounting block 1795, and the screws 1801 project downwardly through the bottoms of the sockets and are threaded into the top of the platen section 1785. Expansive coil springs 1802 surround the screws 1801 within their mounting sockets, and the springs 1802 serve to urge the platen section 1785 upwardly toward an inactive position such that a printing impression will not be made by the platen section 1785 even though the platen supporting frame 1735 is shifted to its active position. The platen section 1785 may be shifted downwardly against the force of the springs 1802 by means of a pair of cam shafts 1805 which are mounted transversely in the mounting plate 1785 so that the lowermost surface of the cam shafts may be rotated into different engaging relationships with respect to certain portions of the platen section 1785. The cam shafts 1805 have flat portions 1806 formed thereon in such a position that when the two flat

portions are located in opposed relation to the platen section 1785, this platen section assumes its retracted position. When the two cam shafts 1805 are rocked in a counterclockwise direction from such a relationship, and to the relationship shown in Fig. 19, the flat sections 1806 are moved out of position, and the cam shafts are effective to move the platen section 1785 downwardly against the force of the springs 1802. This moves the platen section 1785 to its active position of Fig. 19 so that the platen section 1785 is conditioned to produce a printing impression in the event that the platen supporting frame 1735 is moved to its active position. The two cam shafts 1805 are moved in unison through the medium of arms 1807 which are fixed thereto and are connected by a link 1808.

When the arm 1736 is moved upwardly a roller 1809 mounted on an arm 1810 fixed to the left hand cam shaft 1805 engages an abutment surface 1811 formed on the lower edge of a stationary plate 1812, the plate 1812 being mounted on a stationary cross-member 1813 of a frame 1814 which supports the guide rollers 1707 and 1708. Thus in the upward movement of the arm 1736 the stationary abutment 1811 acts on the roller 1809 to shift the cam shafts 1805 to the positions shown in Fig. 19, and as a result the platen section 1785 is invariably located in its active position when the platen supporting arm 1736 is in its elevated position. Hence when the cam shafts 1805 are allowed to remain in this relationship during the next downward stroke, of the arm 1736, the platen section 1785 will be effective to produce a printing impression from the printing device located at printing position V. Provision is made, however, for rocking the cam shafts 1805 in a clockwise direction during the course of a downward movement of the arm 1736, thereby to cause the platen section 1785 to assume its inactive position before the platen supporting arm 1736 reaches the end of its downward stroke. In the present instance this means comprises a swingably mounted arm 1815 suspended from the cross-member 1813 in such a manner that the laterally projecting lower end 1816 thereof may be shifted to a position beneath the roller 1809, thereby to prevent downward movement of the roller 1809 in the course of a rocking movement of a platen supporting arm 1736. The arm 1815 is urged toward an inactive position by means of a spring 1817 which acts between the arm 1815 and a supporting or anchoring rod 1818, and means is provided to shift the arm 1815 to an active position when it is desired to render the platen section 1785 inactive. This means in the present instance comprises a solenoid 1820 having its armature connected by means of a rod 1821 to the arm 1815, and whenever the platen section 1785 is to be rendered inactive, the solenoid 1820 is energized. This shifts the arm 1815 to its active position to thereby cause the roller 1819 to be held against downward movement, with the result that rocking movement is imparted to the cam shafts 1805 to bring the flat sections 1806 thereof into alignment with the opposed upper face portions of the platen section 1785. The platen section 1785 therefore, is retracted to its inactive position and a printing impression is not made from the printing device located at printing position V. In the upward or retracting movement of the platen supporting arm 1736 the abutment 1811 acts upon the roller 1809 to rock the shafts 1805 to the position shown in Fig. 19 and the platen section 1785 is thereby

conditioned to produce a printing impression in the next cycle of operation of platen supporting arm 1736.

The platen section 1787 which is used in printing the numbers N' upon the proof sheet is also mounted for relative shifting to thereby avoid printing of a number in certain cycle of operation of the platen supporting frame 1735. As herein shown an arm 1825 is pivoted at 1826 on the plate 1790, and the arm extends to the left in Figs. 18 and 19 to a point beyond the left hand end of the platen section 1788. The platen section 1787 is supported beneath the left hand end of the arm 1825 so as to project downwardly through a slot 1827 formed in the supporting plate 1790. The platen section 1787 is supported by means of a screw 1828 which extends through the arm 1825 and is threaded into the platen section 1787. By tightening the screw 1828 the platen may be drawn into engagement with a pair of spaced leveling screws 1829 which are associated with the platen section 1787 in a manner substantially similar to the association employed with the leveling screws 1791.

When the platen supporting frame 1735 is rocked in an impression making direction, the arm 1825 of the platen section 1787 is yieldingly restrained against downward movement by means of a spring 1830 which surrounds a link 1831 pivoted at its lower end to the arm 1825. The link 1831 extends upwardly and slidably through an opening in a block 1832 which is mounted on the end of the anchoring rod 1818, and the spring 1830 rests at its lower end on the block 1832. At its upper end the spring acts against a pair of nuts 1833 threaded onto the link 1831. Thus the platen section 1787 tends to remain in an upper or inactive position when the platen supporting arm 1736 is lowered through an impression forming stroke, and means is provided for operatively connecting the platen section 1787 to the arm 1736 when an impression is to be made by the platen 1787. In the platen structure herein illustrated this end is attained through the provision of abutment means carried on the arm 1736 and adapted to be shifted into a position over the arm 1825, thereby to lock the arm 1825 in a predetermined relationship to the arm 1736, and hence the yielding action of the spring 1830 is ineffective to retain the platen section 1787 in its inactive position. In the present instance the abutment means comprises a slide rod 1835 extending slidably through upstanding mounting flanges 1836 and 1837 carried on the plate 1790. The slide rod 1835 has an abutment disc 1838 fixed thereon in such a relationship that it may be shifted from the position shown in Fig. 18 to a position wherein it overlies the arm 1825. Such shifting movement may be imparted to the slide rod 1835 by means of a solenoid 1840 which has its armature 1841 operatively connected to one end of the slide rod 1835. A spring 1842 surrounds the armature 1841 and acts on the armature to normally shift the slide rod 1835 and the disc 1838 to their inactive positions of Fig. 18.

It will be evident that the platen mechanism P-3 provides for selective performance of printing operations by the platen sections 1785 and 1787, and since the platen section 1786 is associated with a hammer type of variable printer, the three classes of data embodied in a proof sheet may be selectively printed with the present mechanism.

As hereinbefore pointed out the hydraulic cylinders of the two platen mechanisms P-2

and P-3 are independently supplied with hydraulic liquid through independently and selectively operable pumps 1720A and 1720B, which as shown in Figs. 20 to 22 are similar in form and construction and are both operated from a drive shaft 1850. The drive shaft 1850 is driven from a motor 1851 through a belted connection 1853 to a drive pulley 1854 fixed on the shaft 1850. The drive shaft 1850 is journaled in three laterally spaced parallel mounting plates 1855, 1856 and 1857 which serve to support the two pumps as well as all of the drive and control mechanism thereof. The three plates 1855, 1856 and 1857 are connected together at their upper and lower ends respectively by end plates 1858 and 1858', and the assembly thus provided is mounted in the frame 1703 by hanger plates 1855'. The pump 1720A is mounted on the upper end plate 1858 so that the pump 1720A projects downwardly through the plate 1858 between the two plates 1856 and 1857, while the pump 1720B is similarly mounted so as to extend downwardly between the two plates 1855 and 1856. Each pump comprises a cylinder 1860 in the lower end of which a piston 1861 is located for longitudinal reciprocation, and thus the upper end of cylinder 1860 forms a pumping chamber 1862. Each pumping chamber is connected to one of the hydraulic platen actuating cylinders, the pump 1720B being connected to discharge into a pipe 1730B which is connected at its discharge end to the passage 1755. The hydraulic connection 1730 which is associated with the inlet passage 1721 is connected to the pump 1720A. The connection of the discharge pipe such as the pipe 1730B to the pump chamber 1862 is accomplished by a fitting 1863 threaded into the end of a cylinder cap 1864. The fitting 1863 connects with a valve chamber 1865' formed in the cylinder cap 1864, and a spring pressed ball check valve member 1865 is mounted within the valve chamber 1865'. The check valve 1865 is connected so as to normally close a relatively large passage 1866 from the valve chamber 1864 to the pump chamber 1862, but in a discharge stroke of the piston 1861 the valve 1865 is unseated and hydraulic liquid is forced under pressure into the valve chamber 1864 and thence into the pipe 1730 and the connected piston and cylinder device. In the return or non-pumping stroke of the piston 1861 the valve 1865 closes, and the return flow of the hydraulic liquid to the pump chamber 1862 must pass through a relatively restricted passage 1867, thereby to produce a controlled return movement of an associated platen structure.

The return spring means which acts upon the supporting arm of the associated platen tends to force the hydraulic liquid back into the pump chamber 1862 so that the piston 1861 is normally urged in a downward direction, and means is provided whereby the piston 1861 may be actuated through an upward or pumping structure. In the present instance this driving means for each of the pumps comprises an eccentric 1870 mounted on an intermediate shaft 1871 so that when the eccentric 1870 is rotated about the axis of the shaft 1871 the eccentric will act upon an opposing cam roller 1872 fixed on the lower end of the associate piston 1861. In the present instance each cam roller 1872 is mounted in a bifurcated bracket member 1873 which is secured by means of one or more bolts 1874 to the lower end of the piston. The return or downward stroke of the piston 1861 is preferably limited so as to slightly

space the roller 1872 from its eccentric 1870 when the eccentric has completed an actuating rotative movement. This end is attained by a stop 1875 mounted on an arm 1876 so that the stop 1875 extends into the bifurcation in the bracket 1873. The arm 1876 is adjustably secured upon an adjacent one of the frame members such as the frame member or plate 1857 by means of a clamping screw 1878 which extends through a slot 1879 in the arm 1876 and is threaded into the frame member.

The intermediate shaft 1871 is constantly driven from the drive shaft 1850 by meshed gears 1890 and 1891 which are fixed respectively upon the shafts 1850 and 1871, and the eccentrics 1870 are, in effect, loosely mounted on the shaft 1871 and are selectively connected to the shaft 1871 when the associated pump 1720A or 1720B is to be operated through a pumping stroke. Such selective connection of the eccentrics 1870 to the shaft 1871 is in the present instance effected by a pair of one-revolution clutches 1895A and 1895B, one of which is allocated to each of the two pumps. The two one-revolution clutches are of the same construction and but one of these clutches will be described. These clutches are of the general character shown in my copending application Serial No. 179,348, filed December 11, 1937, and reference may be made to said application for a more detailed description. Each clutch includes a driving member 1896 pinned to the shaft 1871 so as to rotate constantly therewith, and a driven member 1897 which in the present instance is formed as a sleeve-like extension on the eccentric 1870 to which the particular clutch is allocated. The driving and driven clutch members are provided with inter-engageable clutch teeth 1896' and 1897' located on the adjacent ends of the driving and driven members respectively, and by longitudinal shifting movement of the driven member, the teeth may be engaged so as to cause the associated eccentric 1870 to be driven with the shaft 1871. The driven member 1897 is urged by spring means toward an engaging relationship with respect to the driving member 1896, and for this purpose a bearing plate 1898 is provided about the shaft 1871 adjacent that end of the eccentric which is remote from the driving member 1896. The bearing plate 1898 is located in abutment with a stationary bearing sleeve 1899 which surrounds and supports the shaft 1871, and spring means acts longitudinally of the axis of the shaft 1871 between the bearing plate 1898 and the eccentric 1870 to urge the driven member of the clutch toward its engaged relation. In the present instance the bearing plate 1898 has a plurality of guide plungers 1900 fixed thereon so as to project into guide bores 1901 formed in the eccentric 1870, and a spring 1902 is provided about each guide plunger 1900 so as to act between the bearing plate 1898 and the eccentric to urge the eccentric in a clutch-engaging direction.

Means is provided for controlling the engagement and disengagement of the clutch, and this means includes a radially extending pin 1903 fixed in the driven member 1897, and as the driven member rotates, the pin 1903 moves into engagement with a cam surface 1904 formed on a release or cam plate 1905. The cam surface 1904 is such that as the pin 1903 rides along the cam surface the pin and the associated driven member 1897 are forced in an endwise direction away from the driving member 1896, thereby to cause dis-

engagement of the clutch. At the end of the cam surface 1904 the pin 1903 rides into a recess or pocket 1906 which is so formed and positioned that it serves to terminate and positively stop further rotation of the driven member 1897 of the clutch.

When the clutch is to be again engaged, the release plate 1905 is withdrawn in a direction generally radial with respect to the axis of the shaft 1871, thereby to release the pin 1903 and permit endwise movement of the driven member 1897 into engagement with the driving member 1896. Hence the clutch is engaged and rotative movement of the driven member of the clutch is initiated. Such rotative movement shifts the pin 1903 out of alignment with the pocket 1906 so that the release plate 1905 may then be returned to its original position in engagement with the peripheries of the driving and driven members to be thereby conditioned for releasing the clutch at the end of its one revolution cycle. Such shifting movement of the release plate 1905 is in the present instance obtained by means of a solenoid 1910, one such solenoid being stationarily mounted in association with each of the clutches by means of a mounting bracket 1910'. The armature of the solenoid 1910 has an angular bracket 1911 connected thereto and the release plate 1905 is secured as by rivets to the angular bracket 1911 so as to be properly positioned with respect to the driving and driven members of the clutch.

In the clutch which is herein shown means is also provided for preventing rebound or retrograde movement of the driven member of the clutch after it has been stopped by engagement of the pin 1903 with the pocket 1906. This end is attained through the provision of an abutment plate 1914 which is so mounted that one of its ends overlies the release plate 1905 as shown in Fig. 20 of the drawings. The abutment plate 1914 has an abutment edge 1915 which is shifted into abutment with the trailing edge of the pin 1903 after the pin has engaged with the pocket 1906, thereby to prevent retrograde movement of the driven member of the clutch. In attaining such shifting movement of the abutment plate 1914, the plate is mounted on a flattened side face 1916' of a stub shaft 1916 which extends laterally from the adjacent one of the mounting plates 1855 or 1856. The abutment plate 1914 is held in place on an extending stud 1917 which has a surrounding coil spring 1918 which acts through a spacer washer 1918' on the abutment plate 1914 to urge the same downwardly toward the face of the release plate 1905. Another coil spring 1919 within the spring 1918 extends through the washer 1918' and an aligned opening in the plate 1914 to bear directly on the release plate 1905, thereby to independently bias the release plate toward its normal position. Thus when the pin 1903 engages the cam surface 1904, and starts to ride along said surface, the end of the pin 1903 engages the adjacent or bottom surface of the abutment member 1914 and lifts the abutment member against the force of the spring 1918. When such movement of the pin 1903 has progressed until the pin is seated in the pocket 1906, the spring 1918 acts to quickly return the abutment member to a position wherein the abutment edge 1915 serves to hold the pin 1903 in the predetermined position determined by the pocket 1906.

It will be evident that through selective energization of the solenoids 1910 the two pumps 1720A and 1720B may be selectively operated through the platen actuating cycles. In this con-

nexion it will be observed that the controlled return movement of the associated platen supporting arm which is obtained through the co-operative action of the check valve 1865 and the associated by-pass 1867 prevents the hydraulic return pressure which is induced by the return springs of the platen from causing accelerated movement of eccentric 1870 and its associated member 1897. Such acceleration during the last half of the one revolution cycle of the clutch would of course, be undesirable since it would place excessive strain upon the release plate 1905 and the pin 1903, and such acceleration might result if the hydraulic return pressure were allowed to force the cam roller 1872 against the eccentric 1870. The controlled return flow of the hydraulic fluid results, however, in retarding the return movement of the cam roller 1872 and as a consequence the cam roller is out of contact with the eccentric during substantially all of the last half of the cycle of the eccentric. At the end of this cycle the stop 1875 maintains the cam roller 1872 in a slightly spaced relation with respect to the eccentric 1870 and hence the longitudinal clutch-engaging movement of the eccentric may be readily accomplished through the use of clutch springs 1902 of relatively low tension.

In hydraulic systems of the character herein disclosed it is of course important to eliminate compressible fluid within the hydraulic system, thereby to insure that platen will be actuated through its complete working stroke each time the hydraulic actuating mechanism operates through a working cycle. This end is obtained in the embodiment shown in Figs. 1 to 16 through the air bleed valve 630 and the associated piping connections, but in the present embodiment which is shown in Figs. 17 to 24, this end is obtained through periodically introducing excess quantity of hydraulic liquid into the hydraulic system. Where such an excess of liquid is introduced into the hydraulic system prior to each operating cycle thereof, the desired effectiveness of the hydraulic mechanism is invariably obtained. In the hydraulic mechanism herein disclosed a reserve supply of hydraulic liquid is constantly maintained in a sump 1920 which is provided in the upper end of a casting 1921, the sump 1920 preferably serving as a reserve supply reservoir for both of the pumps 1720A and 1720B. The casting 1921 is secured as by means of bolts 1922 to the lower connecting plate 1858' which extends across and is secured to the lower ends of the mounting plates 1855, 1856 and 1857. At its lower end the casting 1921 has a relatively solid downward extension 1924 which is utilized in providing a pumping means for each of the metering pumps whereby hydraulic liquid from the sump 1920 may be pumped under pressure and introduced into the hydraulic system. To this end the extension 1924 has a downwardly extending bore 1925 formed therein, the bore having a restricted intermediate portion 1926 whereby a pump chamber is formed above the restricted portion, and a valve chamber is formed below the restricted portion. Just above the restricted portion 1926 a sleeve 1927 is mounted in fixed position in the bore 1925, and this sleeve 1927 constitutes the cylinder of a make-up pump. A piston 1928 is adapted to reciprocate in the cylinder provided by the sleeve 1927, and the piston is preferably formed on the lower end of a non-circular guide stem 1929 which rides in the bore 1925 and guides the piston 1928 into the sleeve. Means is provided for actuating the piston

1928 through a suction stroke at intervals which are sufficiently short with relation to the operation of the drive shaft 1871 of the two pumps to insure that the piston 1928 will invariably supply the required make-up liquid to the associated system. In the present instance this means comprises an eccentric 1930 fixed on the shaft 1850 and adapted to engage a cam roller 1931. The cam roller 1931 is fixed on one end of a lever arm 1932 which extends in a generally horizontal direction across the top of the sump 1920. The other end of the lever arm 1932 is pivoted on a pin 1933 which is mounted in an upstanding bearing arm 1934 formed on the side of the sump casting 1921. The lever arm 1932 is located substantially in the same plane as the central axis of the bore 1925, and a vertical link 1935 is connected between the lever arm 1932 and the upper end of the piston 1928. A spring 1936 connected between a lower portion of the arm 1934 and the lever arm 1932 serves to urge the cam roller 1931 into engagement with the eccentric 1930. The eccentric 1930 is constantly rotated in the direction indicated by the arrow in Fig. 23 so that in each revolution of the shaft 1850 piston 1928 is elevated to a point somewhat above the upper end of the sleeve 1927. The eccentric then permits downward or return movement of the cam roller 1931 and the piston 1928 under the biasing action of the spring 1936, and the piston 1928 thereby tends to operate through an active pumping stroke. It will be evident that during the period when the piston 1928 is completely withdrawn from the sleeve 1927, the pump chamber within the sleeve 1927 will be filled by downward flow of hydraulic liquid from the sump 1920. During the active pumping stroke of the piston 1928 a spring biased ball check valve 1938 is unseated and hydraulic liquid is forced downwardly through a connecting fitting 1939 and a make-up pipe 1940. The make-up pipe 1940 is connected at its other end to a fitting 1941 which is threaded into the outer end of the valve chamber 1865'. Hence the make-up liquid which is pumped by the piston 1928 of the make-up pump is forced through the pipe 1940 and into the hydraulic system of the associated pump 1720A and 1720B.

In certain instances the piston 1928 may be forced through but a relatively small portion of its pumping stroke, for it will be evident that when the hydraulic system has been completely filled, or when the piston 1928 is released for pumping movement during the pressure stroke of the associated pump 1720A or 1720B, the spring 1936 will be ineffective to produce pumping movement of the piston. Under such circumstances the piston 1928 remains stationary until the pressure in the system has been sufficiently reduced to enable the spring 1936 to complete the pumping stroke of the piston. As will be hereinafter pointed out, this characteristic of the make-up pumps insures that the associated hydraulic system will be properly and completely filled prior to each pumping stroke of the metering pump 1720A or 1720B thereof.

Each hydraulic system and its associated metering pump 1720A or 1720B are so related that the metering pump in each stroke discharges a predetermined volume of hydraulic liquid which is slightly greater than the volume required to move the platen through its printing stroke. Hence it will be clear that the positive stop means of the associated platen will stop movement of the platen and of the actuating piston 568' or 76

1751 shortly before the completion of the discharge stroke of the pump piston 1861. When this occurs the excess hydraulic liquid is returned to the sump 1920 through a return pipe 1945. The return pipe 1945 is connected to the hydraulic system of the pump 1720A or 1720B through a connecting block 1946 which is in the nature of a T-fitting and is interposed in the make-up line 1940 intermediate its ends. The return line 1945 is connected at its other end to the lower end of the casting extension 1924 by means of a fitting 1947, Fig. 23, through which the liquid to be returned may be forced into the lower end of a relatively restricted passage or bore 1948. At its upper end the passage 1948 enters an enlarged coaxial bore 1949 which serves as a valve chamber for a spring-closed relief valve 1950. The relief valve 1950 has a conical lower end which may be seated in the upper end of the bore 1948 thereby to close the bore. Immediately above its conical lower end the valve member 1950 has a non-circular guiding portion riding against the walls of the enlarged bore 1949 while allowing for upward passage of liquid thereby. A valve stem 1951 is fixed to and extends upwardly from the valve member 1950, and a valve spring 1952 surrounds the valve stem so as to urge the valve 1950 to a seated position. In the present instance the upper end of the spring 1950 bears against the lower end of a screw threaded adjusting stem 1953 which is threaded into a further enlarged upper portion of the bore 1949. The adjusting stem 1953 has a longitudinal groove 1954 through which hydraulic liquid may pass from the more 1948 upwardly into the sump 1920. A tubular actuating member 1956 is connected to the upper end of the adjusting member 1953 by means of a connecting block 1957, and the actuating member 1956 extends upwardly through an opening provided in a cover plate 1958 of the sump and has a knurled actuating head 1959 at its upper end whereby the adjusting member or screw 1953 may be actuated to adjust the tension of the valve spring 1952. Such an adjusted position of the adjusting member 1953 may be preserved by a bar 1961 which surrounds the two actuating tubes 1956 of the two relief valves near the upper ends thereof and has set screws 1962 therein for engaging the tubular members 1956 to prevent rotation thereof.

Means is provided whereby the valve member 1950 may be readily actuated manually either to close the valve or to grind away sediment which may be disposed on the valve or its seat. This end is attained by extending the valve stem 1951 upwardly through screw threaded member 1953, the block 1957 and tubular element 1956. At its upper end the valve stem 1951 is provided with a knurled head 1960 by means of which the valve 1950 may be actuated manually, either longitudinally or in a rotative manner.

The constant pressure relief valve 1950 is so adjusted, by means of the actuating head 1959, that the valve 1950 remains closed until the movement of the platen is terminated by the associated stop means, and at this time the pressure in the hydraulic system increases until the spring 1952 is overcome and the valve 1950 is opened. The excess hydraulic liquid then returns to the sump 1920. In attaining this action the relationship of the piston and cylinder device, as 1750-1751, and the adjustable abutment 1753 is so adjusted that movement of the platen from its retracted position to printing position requires introduction into the cylinder 1750 of a volume of

hydraulic liquid which is somewhat less than the discharge of the metering pump. This difference is preferably less than the output or discharge of the make-up pump, thereby to enable the make-up pump to re-introduce the required amount of liquid in but a single operative stroke.

While the metering pump 1720A or 1720B of a hydraulic system may be started through its operating cycle at any point in the operating cycle of the associated metering pump, it will be observed that the arrangement in the present machine is such that the required excess volume of hydraulic liquid will in every instance be introduced into the hydraulic system between successive periods of high pressure in the system. This end is attained by driving the intermediate shaft 1871 at a speed somewhat slower than the speed of the shaft 1850, thereby to insure that the make-up pump will tend to operate at least once for each cycle of the metering pump. Thus in the present instance the gears 1890 and 1891 are so related that the driving ratio is substantially three-to-two, so that the piston 1928 of the make-up pump is conditioned for operation at least once in each possible period of operation of the metering pump. The tensioning of the operating spring of the piston 1928 may, of course, take place at any point in the cycle of operation of the metering pump, and in the event that the pressure in the hydraulic system is so great as to prevent immediate operation of the make-up piston, such operation is merely delayed until the pressure in the system has been sufficiently reduced to permit the spring to become effective. Such a reduction of the pressure in the system invariably takes place prior to the next cycle of operation of the metering pump so that the resulting operation of the make-up piston introduces the desired excess of hydraulic liquid into the system prior to the next operation of the metering pump. Thus the hydraulic platen actuating means produces proper and effective operation of the platen in each cycle.

The platen PM, as hereinbefore pointed out, is utilized to cooperate with the variable printer VP to print the variable data V on the sheet S, and this platen is also utilized to print the number N on the sheet S through the medium of a numbering mechanism 1965 disposed beneath the platen PM beside the type segments 1706 of the variable printer VP. The platen mechanism PM as herein shown comprises a pair of L-shaped side frames 1966 held in spaced relation by a spacing bar 1967 at one end and by a cross bar 1968 at the other end. At said one end the frame members 1966 have downwardly extending knife edge bearing members 1969 which rest in V-shaped bearing notches 1970 provided on the frame of the variable printer VP. A pivotally mounted latching bar 1971 is engaged with the spacing bar 1967 to hold the platen PM in position on its knife edge bearings.

The cross bar 1968 is utilized as a mounting for a pair of platen sections 1973 and 1974, these two platen sections being utilized to print the number N and the variable data V, respectively. The location of these platen faces on the cross bar 1968 is governed primarily by the desired location of the impressions which are to be formed thereby on the sheet S, and in the present instance the platen section 1973 is disposed to the left and somewhat rearwardly of the platen section 1974, as viewed in Fig. 25, since it is desired to produce correspondingly located impressions N and V on the sheet S. Each of the platen sec-

tions 1973 and 1974 is mounted by means of levelling screws 1975 and a securing screw 1976, the securing screw being utilized to hold the platen sections upwardly against the levelling screws 1975. This arrangement is similar to the levelling arrangement employed in mounting the platen sections 1786 and 1787, hereinbefore described.

In accordance with the present invention the platen PM is actuated through its printing stroke by the same platen actuating means that is used to actuate the platen P-2, and this end is attained by operatively interconnecting the two platens P and PM when a printing impression is to be made by the platen PM. For this reason the knife edge bearings as 1969 of the platen PM are disposed in substantial alignment with the knife edge bearings of the platen P-2, thereby to cause the platen sections 1973 and 1974 to move along a path which is similar to the path of the platen face on section 625 of the platen P-2. It will be understood that when the platen P-2 is actuated through its printing stroke to print the changeable data A on the sheet S there is a printing device D located on the anvil 1705. The printing device advancing means is then operated to advance the printing device D from station III, that is from its position over the anvil 1705, and prior to the time when another printing device is fed into printing position III, the platen P-2 may be actuated without producing either a printing impression or an offset. It is during such periods when a printing device D is not located at station III that the numbering and variable data impressions are made upon the sheet S, and the desired interconnection between the platen P-2 and the platen PM is in the present instance effected by a latch mechanism.

The details of construction and operation of this latch mechanism are illustrated in Figs. 25 to 27 of the drawings, wherein it will be observed that a relatively rigid mounting rod 1978 is secured on the left-hand frame member of the platen P-2 so as to extend to the left, as viewed in Figs. 25 and 27. At its end the mounting rod 1978 carries a pivotally supported latch 1980 having a downwardly facing shoulder 1981, Fig. 26, adapted to engage the upper forward edge of the cross bar 1968. In the event of such engagement of the shoulder 1981 with the cross bar 1968, it will be evident that operation of the platen P-2 through its printing stroke will produce corresponding operation of the platen PM through its printing stroke.

The latch 1980 is normally urged toward such a latching relationship with respect to the platen PM by actuating rod 1983 pivoted at its forward end to the latch 1980 at 1984. The rod 1983 extends rearwardly and slidably through a cross bar 1985 which extends between the side frame members 1966. A spring 1986 surrounds the rear portion of the rod 1983 so as to act between the cross bar 1985 and an abutment 1987 on the rear end of the rod 1983.

The platen PM is normally held in an elevated or inactive relationship by a spring 1988 connected at its upper end to an anchor 1989 on the platen P-2 and connected at its lower end to an anchor 1990 on the adjacent frame 1966 of platen PM. The spring 1988 normally holds the platen PM in such an elevated position that the rear face 1991 of the latch 1980 engages the forward face of the cross bar 1968 of the platen PM. Thus the shoulder 1981 is normally disposed somewhat below the upper face of the cross bar

1968, and when the latch 1980 is to be operatively engaged with the platen PM, the platen PM is actuated slightly in a downward direction to thereby locate the cross bar 1968 somewhat below the level of the shoulder 1981, and while this condition prevails, the latch 1980 is allowed to move rearwardly under the influence of the spring 1986. Cam means is preferably utilized for accomplishing this controlling action, the cam means in the present instance being associated with a control cam shaft 1992 which forms a part of the control means for the sheet feed. The cam shaft 1992 is driven in timed relation to the control mechanism of the machine, and is utilized to control the sheet stop fingers (not shown) and the sheet feeding rollers as 1993. During the time when the platen P-2 is to be actuated independently of the platen PM a rise on cam 1995, fixed on the cam shaft 1992, engages the rear face of a depending cam follower 1996 fixed on the rod 1983 to thereby hold the latch 1980 against engaging or rearward movement. At the time when the follower 1996 is about to ride off of the rise on the cam 1995, a rise on a cam 1997 engages the forwardly projecting foot portion of a bracket 1999 fixed to the cross bar 1985. The cam 1997 thereby acts to shift the platen PM downwardly so that the cross bar 1968 thereof is located below the level of the shoulder 1981 of the latch 1980. Hence when the cam 1995 releases its restraining action upon the follower 1996, the spring 1986 shifts the latch 1980 rearwardly to engage the shoulder 1981 with the platen PM. The platen PM is thus latched to the platen P-2 so that the actuation of the platen P-2 through its printing stroke by its normal actuating means is effective to produce a corresponding printing stroke of the platen PM.

Where a check such as the check S is being produced so as to require but a single impression V and a single impression A, the platen P-2 is operated through but two cycles of operation, in one of which the changeable data A is printed upon the check, and in the other of which the platen PM is simultaneously operated to print the impressions V and N upon the check. It will be understood, of course, that in the event the check were to embody a stub portion requiring duplicate impressions A, V and N, the platen P-2 would be operated four times, in two of which the platen P-2 would operate independently of the platen PM to thereby print the changeable data A once upon the stub and once upon the check, and in the other two of the operations the platen mechanism P-2 would operate the platen PM to make one impression upon the stub and the other impression upon the check. Upon completion of the desired printing stroke or strokes of the platen PM the rise on the cam 1995 engages the cam follower 1996 to disengage the latch 1980 from the platen PM. Thus the changeable data and variable data derived from a single printing and control device D are printed on a check or sheet S, together with an identifying number N. Corresponding impressions are made in each line of the proof sheet by the platen P-3, as will now be explained.

As best shown in Fig. 18, the platen sections 1785, 1786 and 1787 of the platen P-3 are not mounted in alignment since the printing impressions of variable data V' and a number N' made in any particular operation of the platen P-3 pertain to a printing device which follows

the printing device which is then located at station V. As to any particular printing and control device D, the variable data V' derived therefrom is printed on the proof sheet before the printing and control device reaches station V', and prior to the next operation of the platen P-3 the web 901-W is advanced through a line spacing movement, and hence the platen section 1785 is so related to the platen sections 1786 and 1787 as to print the changeable data A' in the same line as the previously printed impressions V' and N'. After the first operation of the platen P-3, all of the platen sections 1785, 1786 and 1787 may be effective in a printing stroke, but in each instance the changeable data A' will be printed from one printing and control device in a particular line on the proof sheet, while variable and numbering data V' and N' pertaining to a succeeding printing and control device will be printed in the next line of the proof sheet. Therefore, the variable data V' changeable data A' that are thus printed in any particular line of the proof sheet are related, which is to say, these data are derived from the same printing and control device.

From the foregoing description it will be apparent that the present invention enables uniform printing impressions to be made from the printing means of printing devices even though there may be a wide variation in the number of printing characters embodied in the printing devices successively passed through the machine. Moreover, this invention enables the platen mechanism to be actuated by hydraulic means, and in particular, this invention enables such actuation to be attained by a closed hydraulic system which facilitates the production of uniform printing impressions. This invention provides a constant make-up supply of hydraulic liquid, and automatic make-up of liquid in the system is attained in such a manner as to insure against objectionable presence of compressible fluid such as air in the system.

The hydraulically operated platen of this invention is so constructed that forces incident to the operation thereof are dissipated in the platen structure itself rather than throughout the frame work of the machine as has been done heretofore. This, of course, materially contributes to the production of neat and uniform impressions irrespective of the number of type characters that are presented to the platen in an impression making operation, and this desirable action is augmented by the manner in which printing pressure is impressed on the platen P by the hydraulic arrangement and is further insured by the positive stopping of the platen when it attains printing position.

While I have illustrated and described selected embodiments of my invention, it is to be understood that these are capable of variation and modification and I, therefore, do not wish to be limited to the precise details set forth but desire to avail myself of such changes and alterations as fall within the purview of the following claims.

I claim:

1. In a printing machine, the combination of a frame, an anvil stationarily mounted on said frame and defining a printing station upon which a printing plate may be supported with its character faces lying in a predetermined plane, a platen having an operative face lying in a plane, and adapted to face the printing plate in a printing operation, said platen being adapted to be

pressed toward a printing plate located at said printing station, a carrying structure upon which said platen is mounted, and means for pivotally supporting said carrying structure comprising knife edge bearings mounted on said carrying structure with their knife edges located in the plane of said operative face of the platen, V-shaped support bearings stationarily mounted on said frame with the throats of said V-shapes located in said predetermined plane, and actuating means operable to force said platen to its printing position by retroactive forces applied between rigid parts of said anvil and said carrying structure.

2. In a printing machine of the character described having guide means along which a series of printing devices may be sequentially fed through a printing station, an anvil associated with said guide at said station with its operative face located in said guide, a shiftable platen positioned in opposed relation to said face for cooperation with said anvil, and platen supporting means comprising a U-shaped rigid structure having the platen fixed on one arm of the U and the other arm of the U located on the opposite side of said anvil, means pivotally mounting said U-shaped structure, and actuating means for said platen interposed between said other arm and said anvil.

3. In a printing machine of the character described having a printing station, an anvil disposed at said station, with its operative face located in said station and substantially in the printing plane, a shiftable platen positioned in opposed relation to said face for cooperation with said anvil, platen supporting means comprising a U-shaped rigid structure having the platen fixed on one arm of the U and the other arm of the U located on the opposite side of said anvil, knife edge means located substantially in said printing plane for pivotally mounting said U-shaped structure, and actuating means for said platen acting on said other arm.

4. In a printing machine of the character described, an anvil and a cooperating platen mounted in a rigid M-shaped member for relative approaching movement to effect a printing relationship therebetween, hydraulic actuating means operable to effect such approaching movement, and positive stop means outside of the printing field including a part of said rigid member to limit such approaching movement.

5. In a printing machine of the character described having a stationary anvil upon which a printing plate may be positioned, a platen mounted for movement toward and away from said anvil for performing a printing operation, a hydraulic piston and cylinder device having its elements operatively connected to said platen and said anvil for actuating said platen through a printing stroke, said hydraulic device having a liquid supply system including a metering pump operable in each cycle to supply a predetermined volume of liquid to said hydraulic device slightly in excess of the volume required to move said platen through a printing stroke, a constant-pressure valve associated with the said supply system, a relief valve associated with the said supply system, a relief mechanism between said pump and said hydraulic device and embodying a chamber into which a limited volume of fluid may flow when said relief mechanism is released, detector means associated with said platen and operable to control the release of said relief mechanism, and means operable upon said relief

mechanism to return the same to its normal relation upon the release of the hydraulic pressure in the system.

6. In a printing machine of the character described, an anvil and a cooperating platen adapted to print from a printing plate, hydraulic actuating means for said platen, a detector element associated with said platen to determine the presence or absence of a sheet in printing position, and a relief valve in said hydraulic actuating system controlled by said detector element to prevent completion of the platen actuation when absence of a sheet is detected.

7. In a printing machine having an anvil and a cooperating platen between which a printing plate may be positioned to make a printing impression from the plate, a rigid frame member upon which said anvil is stationarily mounted, a shiftably mounted support member upon which said platen is supported, hydraulic means mounted on said anvil and operating to move said support member for imparting an approaching movement to said platen, and stop means acting between said members to limit such approaching movement.

8. In a printing machine having a stationary anvil and a platen movable through a printing stroke and a return stroke to effect a printing operation, a hydraulic piston and cylinder actuator operatively connected to said platen to actuate the same through a printing stroke, a metering pump operatively connected to said piston and cylinder actuator to supply liquid under pressure to said actuator, said pump having a liquid supply reservoir within which said pump is mounted, and an air bleed line having an air release port which opens to the atmosphere, said line being arranged to drain overflow liquid into said reservoir.

9. In a machine of the character described for producing business instruments or the like, the combination of means for sequentially feeding unitary printing and control devices or the like successively into sensing and printing positions, each printing and control device bearing printing means and control data, paper supply means, a platen located at said printing position, hydraulic means for actuating said platen including a normally inoperative pump, auxiliary mechanism for operating on the paper controlled by the control data of a printing and control device in sensing position, and means in the general control means of said machine operable to set said pump in operation.

10. In a machine of the character described for producing business instruments or the like, the combination of means for sequentially feeding unitary printing and control devices or the like successively into sensing and printing positions, each printing and control device bearing printing means and control means, a variable printer controlled by the numerical data of a printing and control device in sensing position, means for supplying paper to said machine, a platen located at said printing position, hydraulic means for actuating said platen, including a pump operable only when said platen is to be actuated, and means operable by said variable printer for setting said pump in operation.

11. In a machine for producing business instruments or the like having means for sequentially feeding unitary printing and control devices each bearing printing means and control means successively into sensing and printing positions, a platen located at said printing posi-

tion, hydraulic actuating means for said platen including a hydraulic system having a control element therein, an auxiliary mechanism controlled by the control means of a printing and control device in sensing operation, and means in said auxiliary mechanism operable to control said control element of the hydraulic system to cause operation of said hydraulic actuator.

12. In a printing machine, means for sequentially feeding unitary printing and control devices each bearing printing means and control means into printing position in the machine, a plurality of mechanisms for operating on a sheet of paper fed into the machine, one of said mechanisms being operable under the control of the control means on said printing and control devices, means for controlling the operation of other of said mechanisms, a platen at said printing position, a platen actuator, and means operable by said last-named controlling means for controlling the operation of said platen actuator.

13. In a printing machine of the character described having a printing station, an anvil associated with said station, a shiftable platen positioned in opposed relation to said anvil for cooperation therewith, and platen supporting means comprising a U-shaped rigid structure having a pair of substantially parallel arms and a connecting member therebetween at one end of said arms, said platen being fixed on one arm of the U and the other arm of the U located on the opposite side of said anvil, means pivotally mounting said U-shaped structure comprising mounting arms projecting laterally from said connecting member in a rigid relation thereto and having bearing means at the ends thereof, at least one of said mounting arms having a slot therein substantially parallel to the axis defined by said bearing means, an inked ribbon extending through said slot and across said anvil, and actuating means acting on said other arm for actuating said U-shaped rigid structure.

14. In a printing machine of the character described having a guide along which printing devices may be advanced to a printing station, an anvil associated with said guide at said station, with its operative face located in said guide, a shiftable platen positioned in opposed relation to said face for cooperation with said anvil, and platen supporting means comprising a U-shaped rigid structure having a pair of substantially parallel arms and a connecting member therebetween at one end of said arms, said platen being fixed on one arm of the U and the other arm of the U located on the opposite side of said anvil, means for pivotally mounting said U-shaped structure comprising mounting arms projecting laterally from said connecting member in a rigid relation thereto and having bearing means at the ends thereof, and actuating means acting on said other arm for actuating said U-shaped rigid structure.

15. In a printing machine of the character described having a stationary anvil upon which a series of printing plates may be positioned in sequence, a platen mounted for movement toward and away from said anvil for performing a printing operation, and a hydraulic piston and cylinder device having its elements operatively connected to said platen and said anvil for actuating said platen through a printing stroke, said hydraulic device having a liquid supply system including a metering pump operable in each cycle to supply a predetermined volume of liquid to said hydraulic device slightly in excess of the

volume required to move said platen through a printing stroke, a constant pressure relief valve associated with the said supply system, an overflow sump into which liquid is discharged from said relief valve, and a make-up pump operable at intervals to pump liquid from said sump into said supply system.

16. In a printing machine of the character described having a stationary anvil upon which a printing plate may be positioned, a platen mounted for movement toward and away from said anvil for performing a printing operation, a hydraulic piston and cylinder device having its elements operatively connected to said platen and said anvil for actuating said platen through a printing stroke, positive stop means operable to limit the stroke of said platen toward said anvil, said hydraulic device having a liquid supply system including a metering pump operable in each cycle to supply a predetermined volume of liquid to said hydraulic device slightly in excess of the volume required to move said platen through a printing stroke, a liquid supply reservoir, a pressure relief passage including a constant-pressure relief valve connected between the said supply system and said reservoir and through which the excess volume of fluid may return to said reservoir after said stop means has terminated movement of said platen, and means operable at least once between successive open periods of said relief valve to introduce such an excess volume of liquid from said reservoir into said system.

17. In a printing machine through which printing devices are passed successively to printing position, an impression means movable from a retracted position through a predetermined and positively limited printing stroke into printing cooperation with a printing device at printing position, an hydraulically operated actuating means connected to said impression member and operable by hydraulic liquid under pressure to actuate said impression member through said printing stroke, a liquid supply reservoir, and a pressure system for said hydraulically operated actuating means comprising a metering pump connected to discharge to said hydraulically operated actuating means and operable in a predetermined pumping cycle to discharge a volume of liquid at least slightly in excess of the volume required to actuate said impression member through said printing stroke, a constant pressure by-pass connected from said system to said reservoir and through which such excess of liquid may return to said reservoir upon completion of said printing stroke, and a make-up pump yieldingly actuated in its operative pumping stroke and operable to pump liquid from said reservoir into said system.

18. In a printing machine through which printing devices are fed to printing position, impression means mounted for movement from a retracted position through a printing stroke toward and into printing cooperation with a printing device at printing position, abutment means positively limiting said printing stroke, hydraulically operated actuating means operatively connected to said impression member for actuating the same through said printing stroke, spring means for operating said impression member through a return stroke to said retracted position, a liquid supply system for said hydraulically operated actuating means operable in each cycle to supply a predetermined volume of hydraulic liquid at least slightly in excess of the volume required to move said impression mem-

ber through said printing stroke, a liquid supply reservoir, a constant pressure by-pass from said system to said reservoir, a constantly operating drive shaft, a driving connection from said drive shaft to said pump including one revolution clutch, a make-up pump to which liquid is supplied from said reservoir and discharging through a check-valved connection into said system, spring means operable to actuate said make-up pump through its discharge stroke in one direction and constructed and arranged so that when once tensioned it is maintained under tension until said make-up pump has been operated through its pumping stroke, and means operable in timed relation to the rotation of said drive shaft to tension the spring means of said make-up pump.

19. In a printing machine through which printing devices are passed successively to printing position, an impression means movable from a retracted position through a predetermined and positively limited printing stroke into printing cooperation with a printing device at printing position, an hydraulically operated actuating means connected to said impression member and operable by hydraulic liquid to actuate said impression member through said printing stroke, a liquid supply reservoir, a pressure system for said hydraulically operated actuating means comprising a metering pump connected to discharge to said hydraulically operated actuating means and operable in a predetermined pumping cycle to discharge a volume of liquid at least slightly in excess of the volume required to actuate said impression member through said printing stroke, a constant pressure by-pass connected from said system to said reservoir and through which such excess of liquid may return to said reservoir upon completion of said printing stroke, and a make-up pump operable once each time the pressure in said system falls from its high level determined by said constant pressure by-pass to a predetermined lower-level to pump liquid from said reservoir into said system.

20. In a printing machine having a stationary anvil upon which a series of printing plates may be positioned in sequence, a platen mounted for movement toward and away from said anvil for performing a printing operation, and hydraulically operated actuating means operatively connected to said platen and said anvil for actuating said platen through a printing stroke, said hydraulically operated means having a liquid supply system including a metering pump operable

in each cycle to supply a predetermined volume of liquid to said hydraulic device slightly in excess of the volume required to move said platen through a printing stroke, a constant pressure relief valve associated with the said supply system, an over-flow sump into which excess liquid is discharged from said system through said relief valve, and a make-up pump operable at least once each time the pressure in said system falls below a predetermined level to pump liquid from said sump into said supply system.

21. In a printing machine having an impression forming member shiftable through an operating cycle including forward and return strokes, hydraulically operable actuating means operatively connected to said member for actuating said member through its forward stroke, spring means for operating said member through its return stroke, a metering pump having a piston and cylinder, a common supply and return line from said cylinder to said hydraulically operable actuating means to provide a hydraulic system, means for supplying hydraulic liquid to said system during rest periods of said pump, driving means for said pump including a one-revolution clutch, and means including a check valve to control return flow of liquid to said cylinder to thereby prevent undue strain upon said one-revolution clutch when it disengages at the end of its cycle.

22. In a printing machine having an impression forming member shiftable through an operating cycle including forward and return strokes, hydraulically operable actuating means operatively connected to said member for actuating said member through its forward stroke, spring means for operating said member through its return stroke, a metering pump having a piston and cylinder, a common supply and return line from said cylinder to said hydraulically operable actuating means to provide a hydraulic system, means for supplying hydraulic liquid to said system during rest periods of said pump, driving means for said pump including a one-revolution clutch, an eccentric driven by said clutch and a follower means on said piston engageable by said eccentric to actuate said piston, and means including a check valve to control return flow of liquid to said cylinder to thereby prevent acceleration of said eccentric and undue strain upon said one-revolution clutch when it disengages at the end of its cycle.

WALTER T. GOLLWITZER.
